tion of Massachusetts

Application December 13, 1951, Serial No. 261,493

43 Claims. (Cl. 51—91)

1

This invention relates to the shaping, as by grinding or other suitable means for cutting or removing metal, of surfaces such as the back or convex face of a turbine or like blade where that surface, while "straight line faired," is, geometrically speaking, generated by the movement of a straight line whose ends move along respectively different curved paths of different and varying relative radii or radial distances from a given axis and at varying relative instantaneous rates.

One of the objects of this invention is to provide a practical and dependable method and apparatus for efficiently producing surfaces of the above-mentioned character in objects, usually made of metal, such as turbine blades. Another object is to provide a method and apparatus of the just-mentioned character capable of shaping surfaces in such articles uniformly and in a manner dependably to achieve quantity production of such objects. Another object is to provide a simple and practical apparatus for facilitating carrying on of the just-stated method.

Another object is to provide a grinding apparatus for producing in objects such as turbine blades so-called convex surfaces of the above-mentioned peculiar characteristic of conformation. Another object is to provide such a grinding machine constructed and operated to produce and uniformly reproduce such surfaces in such objects in a reliable and efficient manner to facilitate production of such articles rapidly and thus lend itself to quantity production thereof.

Another object is to provide devices and mechanisms in the form of individual units or subunits for mounting and controlling the object or objects in which the above-mentioned surface is to be formed, so constructed and arranged that they are speedily and readily adapted or attachable to certain known forms of metal-removing machines such as certain types of grinding machines, thus readily converting the latter for production of the above-mentioned peculiar surfaces in articles such as turbine blades.

Another object is to provide apparatus of the above-mentioned character that will have a substantial range of flexibility of arrangement or construction or adjustment to meet the varying requirements met with in the production of articles of the above-mentioned nature, particularly turbine blades, wherein, as for different stages or different turbine capacities, a substantial range of dimensionally different articles have to be produced though all of them have a surface of the above-mentioned peculiar geometric characteristics, with even those characteristics varying or changing according to circumstances.

2

Other objects will be in part obvious or in part pointed out hereinafter.

The invention accordingly consists in the features of construction, combinations of elements, arrangement of parts, and in the several steps and relation and order of each of the same to one or more of the others, all as will be illustratively described herein and the scope of the application of which will be indicated in the following claims.

10 In the accompanying drawings in which is illustratively shown a preferred embodiment of the mechanical features of this invention and in which similar reference characters refer to similar parts throughout the several views,

15 Figure 1 is a small-scale front elevation of the machine for producing, in work-pieces such as turbine blades, surfaces of the above-described characteristics;

20 Figure 2 is a small-scale diagrammatic representation, in elevation, of a turbine blade blank on which the above-mentioned surface is to be formed;

25 Figure 3 is a diagrammatic perspective view of only the blade portion of the blank of Figure 2, to indicate diagrammatically some of the geometric peculiarities of the surface to be formed;

30 Figure 4 shows diagrammatically the external and internal contours of the blade as seen from the right in Figure 3 and, more particularly, is intended to show the curved line along which the right-hand end, as seen in Figure 3, of the straight-line generator moves;

35 Figure 5 is a view similar to that of Figure 4, being a projection of the left-hand end of the blade of Figure 3, to show diagrammatically the different curvature along which the left-hand end, as seen in Figure 3, of the straight-line generator of the convex surface moves;

40 Figure 6 is a large-scale horizontal sectional view as seen along the line 6—6 of Figure 1 showing certain features of head stock and tail stock units, with the work-piece supported thereby, in operative relation to the grinding wheel, being in the form, respectively, of a left-hand form control and a right-hand form control for shifting, respectively differently, the left-hand and right-hand ends of the work-piece;

45 Figure 7 is a horizontal large-scale sectional view as seen along the line 7—7 of Figure 1 showing certain features of construction of a power-drive head or unit, for driving the controls of the head stock and tail stock units;

50 Figure 8 is a large-scale end elevation of the power-drive head or unit as seen from the left in Figure 1;

55 Figure 9 is a large-scale plan view of the tail

stock control unit as seen along the line 9—9 of Figure 1;

Figure 10 is a large-scale vertical sectional view through the tail stock control unit as seen along the line 18—19 of Figures 1, 6, and 9;

Figure 11 is a fragmentary vertical sectional view of a roller mounting as seen along the line 11—11 of Figure 10;

Figure 12 is a transverse vertical sectional view, on a reduced scale, through the grinding wheel slide and wheel feeding mechanism, substantially as seen along the line 12—12 of Figure 1, certain parts being omitted;

Figure 13 is a fragmentary elevation, on a larger scale, as detached from Figure 6, showing the work-holder or arbor which supports two work-pieces or blades and which is carried in the controllably displaced supports provided by the left-hand and right-hand control units or stocks;

Figure 14 is an elevation thereof as seen along the line 14—14 of Figures 13 and 6;

Figure 15 is an end elevation thereof as seen from the right in Figure 13;

Figure 16 is a diagrammatic representation of the relationships between various parts of the apparatus and the work-piece showing the relative positions of the parts at the commencement of a contour grinding operation and the work-piece; and

Figure 17 is a diagrammatic representation like that of Figure 16 but showing the relative positions of the various parts at the conclusion of a contour grinding operation on the work-piece.

As conducive to a clearer understanding of certain features of this invention, reference might first be made to Figures 2—5; in Figure 2 I have diagrammatically indicated, and designated as a whole by the reference character T, a turbine blade member comprising a blade B whose external and generally convex face is to be shaped, having integrally formed with it and at its respective ends block-like elements A and C both of which may be given any needed or desired conformation appropriate to serve as a means for mounting the blade unit T in the turbine structure and which when so conformed, as by machining or grinding or the like, serve as engageable means by which the blade unit may be supported and positioned for machining, grinding, or otherwise shaping the surfaces of the blade B itself; sometimes only one of such block-like end elements is required for mounting the blade unit in the turbine structure, and in such case the other is simply cut off upon completion of the blade-surface shaping operations. The blade B, diagrammatically shown on a larger scale in Figure 3, is of curved cross-section and may be of varying thickness. It has an inner curved face IF which may be generally considered as concave and which may be shaped in any desired way. Its external face F, in general convex and which is to be shaped according to this invention, is "straight line faired," being generated by movement of a straight line with its ends moving along two curved paths of different and varying relative radii or radial distances from a given axis and at varying relative instantaneous rates. If the surface is thus regarded as being made up of straight lines, the latter are thus never parallel to each other though portions of the surface, according to design or circumstances, may be truly cylindrical or frusto-conical where, throughout two corresponding portions of the two paths through which the ends of the straight

line move, those two portions are equal or geometrically similar and the respective rates of movement therealong of the ends of the generating line are the same.

5 In Figure 3 the lines E are intended diagrammatically to represent not all but only successive positions of the generating straight line so as to indicate this peculiar condition of straight line fairing where the straight lines are not parallel in some regions and may be parallel in other regions. In Figure 3 the curved paths along which the respective left-hand and right-hand ends of the line E move are indicated at G and H, each beginning at the leading edge 20 and each terminating at the trailing edge 21 of the blade B. At the leading edge 20 the straight-line end of the surface F may merge, in suitable curvature, into the inside face IF of the blade, and at the trailing edge 21 the other straight-line terminus of the face F may similarly merge, but usually at a lesser radius of curvature, into the inside face IF, or the two faces may simply intersect each other where it is desired at the trailing edge to materially taper off the thickness of the blade. While in Figure 3 the respectively different paths G and H are indicated in diagrammatic perspective, they are shown in elevation or in development in Figures 5 and 4, respectively, all three figures, as shown, being related to a datum line or axis O—X with relation to which, also, the faces, surfaces, or other configurations needed for the block-like end elements A and C are formed so that by suitably engaging and positioning the parts or faces of the end elements A and C, as in a work-holder W (Figure 6), the axis O—X may be fixedly positioned in relation to the work-holder itself.

As is later pointed out, the work-holder W, which is rotatable, is constructed to have an axis of rotation, and by the just-described relationships of the parts of the blade end elements A and C with respect to the axis O—X, the blade member T may be readily located and secured in the work-holder itself, with the axis O—X coincident with the axis about which the work-holder is constructed to rotate.

The curved lines or paths G and H represent the section contours for the external face of the blade B at the respective ends of the latter and, as above indicated, the surface F is to be determined by straight lines joining the contour section lines G and H even though, in part or in whole (according to design or circumstances), successive lines are not parallel to each other and the angularities between successive lines and the radial distances of their respective ends from the axis O—X differ at the left-hand end and the right-hand end of the blade B and may so differ in uniform increments or even in irregular increments per unit of length along the contour sections G and H.

Illustratively, referring to Figures 4 and 5, the surface F is to have an upper portion F^1 of the same radius r throughout an angle x at the right-hand end and throughout the angle x^1 at the left-hand end, with angle x^1 greater than angle x and with the vertical plane through the bisectors of these two angles coincident with the axis O—X, the center from which the radius r is taken being in that vertical plane but spaced upwardly from the axis O—X. The portions of the section contours G and H subtended by the angles x^1 and x , respectively, may thus each be said to have a point of maximum vertical displacement from the axis O—X, and the line joining these two

points, being in the above-mentioned vertical plane, is parallel to the axis O—X, but to either side of that vertical plane the surface portion F¹ falls off at successively shorter distances from the axis O—X but throughout a greater angle x^1 at the left-hand end than the angle x at the right-hand end. The over-all vertical dimension of the section contour H at the right end, represented by the reference character z^1 , is greater than the corresponding dimension z at the left end, and the spacing y^1 from the above-mentioned vertical plane of the lower terminus of the section contour H at the right end is greater than the corresponding displacement y of the lower terminus (trailing edge) of the section contour G at the left end because of the desired straight line faired portion F² of the external face F of the blade B. Throughout the portion F² therefore the distances in radial directions from the section contours G and H to the axis O—X change, not only throughout the corresponding portions of the section contour but also may change differently or at a different rate in the one section contour from the change in the other, all in turn modified by the fact that the peripheral extent of the surface portion F² at the right end section contour H is greater than that at the left end section contour G. It is this peculiar type of straight line faired surface which the blade member T of Figure 2, usually a forging, is to be given after the block-like end elements A and C thereof have had suitable parts or surfaces thereof machined or otherwise finished in geometric and dimensional relation to the axis O—X.

In producing the above-described illustrative geometric straight line faired surface F, I prefer to remove metal from the outer convex portions of the blade B by a suitable cutting tool, preferably by grinding, utilizing preferably a peripherally acting grinding wheel whose peripheral face can be trued to true cylindrical form, with each straight-line element of the resultant cylindrical grinding wheel face parallel to the axis of rotation of the grinding wheel; such a grinding wheel is indicated in the drawings (Figures 1, 6, and 12) by the reference character 22 and, as indicated in Figure 6, it is preferred that the axial dimension of the grinding wheel 22 be substantially the same as the length in an axial direction of the blade B (Figures 2 and 3) whose surface F is to be shaped or formed; in practice, however, the grinding wheel face is of a width slightly less than the axial dimension of the blade B by an amount, for example, on the order of $\frac{3}{16}$ of an inch or so, in order that the grinding wheel may be given axial strokes of reciprocating movement of that length for better grinding action and longer wheel life and also to avoid grinding wheel marks in the surface of the work-piece. In constructing the apparatus I prefer to employ a number of elements of any suitable known or standard type of grinding machine, such as that disclosed in Patent No. 2,522,485 to Silven et al., issued September 12, 1950, to which reference may be had for details of construction and of operation and control of such selected elements. The latter include a base 23 provided with a longitudinally extending V-way 24 and a companion flat way 25 (see Figure 12) by which a longitudinally slidable or reciprocable table 26 is supported and guided for movement; since, for purposes of the present invention, the table 26 need not partake of power-driven reciprocation or travel, the corresponding table 75

drives and controls of the Silven patent may be omitted or simply not utilized and use can be made only of the manual traverse wheel 27 (Figure 1) which is operatively connected in conventional manner to rotate a gear mechanism which meshes with a rack bar 28 (Figure 12) that extends longitudinally of and depends from the underside of the table 26. Any suitable or conventional means may be employed to lock the table 26 in selected position.

The grinding wheel 22 is carried on one end of a spindle 30 (Figure 12) mounted in suitable bearings in a grinding wheel slide 31 (Figures 1 and 12) which is slidably mounted in usual manner on a pair of rearwardly and hence transversely extending flat and V-ways 29 so that the grinding wheel is movable toward and away from the longitudinal table 26 (Figure 12) or toward and away from the observer viewing Figure 1, the axis of the grinding wheel spindle 30 being parallel to the line of longitudinal traverse of the table 26. The wheel spindle 30 is preferably driven by an electric motor 32 (Figure 1) carried by the wheel slide 31 by driving V-belts 33 connecting motor pulley 34 with pulley 35 which is carried by the other end of wheel spindle 30.

Wheel slide 31 may be fed toward or away from the front table 26 by a feed screw 36 (Figure 12) journaled in anti-friction bearings 37 and 38. The wheel slide 31 is provided with a depending half-nut 40 which meshes with the feed screw 36 and accordingly the wheel slide 31 and its grinding wheel 22 partake of movement toward or away from the front table 26 if the feed screw 36 is bodily moved (hydraulically, for example), or if the feed screw 36 is given a rotary movement, as, for example, by means of a manual operable feed wheel 41 (Figures 1 and 12) mounted at the front of the machine base 23 and provided with suitable driving connections with the feed screw 36. The means for hydraulically actuating and controlling the wheel slide 31 and the mechanism connecting the feed screw 36 with the hand wheel 41 may be substantially the same as those shown and described in the above-mentioned Silven patent.

On the table 26 I mount, preferably detachably, suitable subunits for supporting and controlling the arbor or work-holder in which one or more blade elements T (Figure 2) are secured; these subunits are preferably so constructed that they may replace, or be replaced by, other subunits or heads constructed to effect other kinds and types of grinding operations by the grinding wheel 22, and such subunits may be directly or indirectly supported by the table 26. For purposes of illustration and not by way of limitation, the table 26 may support, substantially throughout its length, a swivel table 42 (Figure 1) by which, as is usual in the case of certain grinding operations for such other subunits or heads, the alignment of such other heads relative to the grinding wheel axis or relative to the longitudinal path of travel of the table 26 may be given an angularity or inclination about a vertical axis, an axis usually provided by a suitable pivotal connection between the two tables in the form, for example, of a heavy cylindrical block or stud indicated at 43 in Figure 1, there being clamping devices 44 at the respective ends of the two tables to fix the swivel table 42 in the desired relation to the sliding table 26. For purposes of the present invention, the swivel table 42, if employed and where the heads or subunits of my

invention are not secured directly to the sliding table 26, is fixed in a position of zero angularity relative to the slide table 26; its longitudinally extending guide surfaces, clamping grooves, or clamping angularities by which the subunits are secured thereto therefore extend parallel to the grinding wheel axis and parallel to the line of longitudinal traverse of the slide table 26. As shown in Figure 10, the upper face 42^a of table 42 is inclined downwardly and toward the rear of the machine as the latter is viewed in Figure 1, and its front face 42^b is machined at an acute angle to form a V-shaped aligning guide with which the various heads or subunits interfit in that they have corresponding V-shaped recesses or slideways; at its rear longitudinal edge the table 42 is also given a V-shape but of an angle so that clamping elements 45, controlled by clamping screws 46 and carried by the various subunits, may coact therewith to fasten the various heads or subunits in selected position lengthwise of the table as well as to fix them in accurate alignment with each other.

In the preferred embodiment of my invention, to the table 42 I secure and align with each other, as just described, three heads or subunits generally indicated by the reference characters 51, 52, and 53 comprising, respectively, a power-drive head, a head stock control unit, and a tail stock control unit, of which the latter two are spaced apart lengthwise of the machine to provide for the entry therebetween of the cutting tool or grinding wheel 22 and to provide ample space to rotatably support therebetween the arbor or work-holder generally indicated by the reference character W, all as is better shown in plan in Figure 6 and in front elevation in Figure 1. In the illustrative embodiment the work-holder W is constructed to fixedly secure in position and on two opposite sides thereof two blade members T (Figure 6) in a manner to bring the axes O—X (Figure 3) thereof into coincidence with each other and with the axis, hereinafter also designated O—X, of the work-holder W, the axis of the latter being fixed by the provision of journal boxes JL and JR in respective ends of the work-holder W which are provided with bearing recesses that are of spherical contour or section, presenting bearing surfaces which are substantially zones of spheres whose axes are aligned or coincident; they are preferably of substantial radius, as is better indicated in Figures 13 and 14, to provide substantial areas of bearing surface for the reception, respectively, of the ball or spherical ends 54 and 55 of the tapered centers CL and CR (Figure 6) carried, respectively, by the head stock control unit 52 and the tail stock control unit 53.

Journal boxes JL and JR may be made of any suitable material having suitable hardness or wear resistance and hence long life, and as shown in Figures 6 and 13-15 they are set and fixed in suitable recesses in the respective ends of the work-holder W. Their spherical-sectioned bearing surfaces, by the line joining the aligned axes of the spheres of which they are zonal sections, fix and determine an axis of rotational support for the work-holder W, and in securing the blade members T, T to the latter the axes O—X of the blade members are brought into coincidence with each other and with that work-holder axis. As indicated in broken lines in Figures 6 and 13, these journal boxes JL and JR, at the respective bottoms of their bearing recesses, are provided with straight cylindrical recesses of lesser radius,

as by drilling, to accommodate or receive particles of foreign matter so as not to interfere with the spherical-surface contacts which the ball-like center ends 54 and 55 are to make with the journal bearing surfaces.

The resultant ball and socket connection and support at each end of the work-holder W permits precise shifting, and control of shifting, of each end of the axis O—X of the work-holder W by controlled related but independent shifting of the centers CL and CR and hence of their respective ball ends 54 and 55, in all directions transversely of the general line of the axis of the work-holder W, in the preferred manner later described in detail and in relation to the grinding line of contact GL of the grinding wheel 22, that being, as later explained, always that straight line of the cylindrical face of the grinding wheel that falls in the same horizontal plane with the axis of the grinding wheel spindle 30, the head stock and tail stock units 52 and 53 being constructed to present the universally movable centers CL and CR, while in general axial juxtaposition to each other as shown in Figure 6, at a height that is in the region of the horizontal plane through the grinding wheel axis and the grinding wheel contact line GL. These ball and socket supports and connections permit the coincident axes of the work-holder W and of the supported blade members T to be given a wide range of tilting both horizontally and vertically, in the same or different degrees as well as directions at the respective ends thereof, to bring any straight fair line to be ground in the blades B always in coincidence with the horizontal straight grinding line of the grinding wheel 22; at the grinding line GL the grinding wheel always cuts a straight horizontal line in the work-piece or blade B, and by moving the ball-ended centers CL and CR independently but in relation to each other while slowly rotating the work-holder and blade, the common axis O—X is shiftable and tiltable, relative to the fixed horizontal grinding line GL of the grinding line GL, so as to successively present to the grinding line elemental portions of the blade B, such as the elements E of Figure 3, to produce the straight line faired face F. Depending upon the desired character of the face F, of which one illustration is described above, the axis O—X of the work-holder W may thus be made to assume a wide variety of relationships to the fixed horizontal straight grinding line GL; one end of that axis may be higher or lower than the other and displaced inwardly toward the grinding wheel more or less than the other, in which case it is never parallel to the grinding line GL while at other times it might be parallel to the grinding line, and then again it might fall in the same horizontal plane with the grinding line GL but be tilted to the latter, or it might fall in a vertical plane parallel to the horizontal grinding line but be tilted to the horizontal. By coordinating physical displacement or movement of the ball-ended centers CL and CR, preferably by displacing each always parallel to itself, and in coordinated and related closed paths of movement for the ball ends, the axis O—X of the work-holder and of the two accurately-diametrically opposed blade members T, T may be given such shifts and inclinations relative to the grinding line GL as have just been described and in such sequences as to be capable of producing a wide variety of straight line faired surfaces having peculiarities of successive curvatures and angu-

larities relative to the axis O—X, such as those above mentioned.

In the mounting and displacement control of the centers CL and CR, the head stock control unit 52 and the tail stock control unit preferably embody a number of structural features that are similar and in some instances identical, except that one is constructed left-hand and other is constructed right-hand. The units 52 and 53 comprise casing-like frames or housings 56 and 67 provided with bottom walls that are inclined and shaped to interfit with and be clamped to the table 42 as earlier above described and as shown in Figure 10 in connection with the tail stock unit 53, being thereby accurately aligned and also adjustably positionable in relation to each other and lengthwise of the table 42. They have upstanding vertical walls, some of which are broken away or provided with suitable openings, and each is provided with a removable top cover plate 58 and 59 (Figure 1). As shown in Figure 6, the ball-ended centers CL and CR are supported to project toward each other through relatively large openings in the adjacent end walls of the frame housings 56 and 57, thus providing ample clearance for freedom of displacing movement of each center in all directions and preferably always parallel to itself. The left-hand center CL is taper-fitted in usual manner into the right-hand end of a driven shaft 60 mounted for displacement in all directions parallel to itself, and the right-hand center CR is taper-fitted into the left-hand end of an axially slidable sleeve 61 which is also supported for displacing movement in all directions parallel to itself. The supports for the shaft 60 and the sleeve 61, for displacing movements, are substantially identically constructed and it will suffice to describe in detail the supporting structure for one of them, namely, the one associated with the tail stock control unit 53, better shown in Figures 9 and 10. In the main, each support comprises two pivotally connected carrier links which, for the tail stock unit, are shown in Figures 9 and 10 at 62 and 63. Link 62 is preferably in the form of a relatively heavy casting of substantial length and breadth (see Figure 9) and extends in a general horizontal direction (Figure 10) within and across the upper portion of the frame housing 57, just under the cover plate 59, and at its front end is pivotally supported by the frame housing 57 to swing about an axis parallel to the interfitting guideways and guides of the frame housing and the table 42 (Figure 10), that axis being therefore parallel to the grinding line GL of the wheel 22 and also parallel to the grinding wheel spindle axis. The pivotal support is preferably by way of bearings of substantial axial spacing, thus to resist the reaction of stresses tending to twist the pivoting axis out of the just-described parallelism, and may be provided and constructed as is better shown in Figure 9, wherein in the forward end of the broad link 62 is bored out as at 64, with the edge walls of the bore slotted as is better shown at 65 in Figure 10, opposed parts of the slotted bore wall being provided with clamping screws 66 to draw them toward each other. Into opposite ends of the slit bore 64, stud shafts 67 and 68 (Figure 9) are inserted which at their respective outer ends carry and have secured the inner races of combined radial and thrust roller bearings 71 and 72, the outer races of which are seated and secured in counterbores 73 and 74, respectively formed in the opposite end walls of the frame housing 57. The two stud

shafts 67 and 68 are of reduced diameter intermediate their ends so as to provide spaced clampable portions that neatly fit the bore 64 and are located, as indicated in Figure 9, in those regions where the axially spaced clamping screws 66 are effective to strain the slit bore walls toward each other for good clamping action. This arrangement insures better accuracy of alignment of the stud shafts and their end bearings 71 and 72 coaxially with the bore 64 and permits some adjustment of the spacing between the end bearings 71 and 72 whose outer races are held against axial shift by annular flanges on the closure plates 75 and 76 that close over the outer ends of the end wall bores 73 and 74 and which are secured to the end walls in any suitable way, as by screws.

From the just-described pivotal support the carrier link 62 extends toward the rear wall of the frame housing 57 and it is bored out at its rear end, as at 77, with the axis of the bore parallel to the axis of bore 64 at the front end. The rear end wall of bore 77 is longitudinally slit, as at 78 (Figure 10), the opposed slit wall portions being provided with clamping screws 89 (Figure 9) to clamp, coaxially with bore 77, two stud shafts 81 and 82 received into the bore from opposite ends thereof and of reduced diameter intermediate their ends for better precision of clamping; the outer ends of stud shafts 81 and 82 have secured thereto the inner races of combined thrust and radial roller bearings 83 and 84 which by this construction are also of substantial axial spacing.

The outer races of the bearings 83 and 84 are received in suitable bores and held and positioned by annularly flanged plates 85 and 86, respectively, formed in the parallel axially spaced upwardly extending arms 63^a and 63^b of the carrier link 63 which is substantially H-shaped, the horizontal or cross-bar portion of which is shown in cross-section at 63^c in Figure 10. The carrier link 63 extends vertically and downwardly from the rear end of the horizontal carrier link 62 (see Figure 10) and by the above-described pivotal connection between the two, the axis about which link or arm 63 can swing is parallel to the axis of pivoting of the link 62.

The downwardly extending and axially spaced arms 63^a and 63^b (Figures 10 and 6) are bored out to receive and have secured coaxially therein a heavy sleeve 87 whose axis is parallel to the axis about which the upper end of the pendent link 63 pivots, and it is within this sleeve 87 that the sleeve 61 which carries the ball-ended center CR is slidably but coaxially mounted.

By means of the pivotally connected carrier links 62 and 63 the ball-ended center CR and its axis may be shifted in all directions as viewed in Figure 10, and for any such direction the pivotal support for the horizontal link 62, permitting up and down oscillation, supplies the vertical component and the pivotal connection between the pendent link 63 and the horizontal link 62, permitting displacement or oscillation horizontally, supplies the horizontal component, the axis of the center CR, however, always remaining parallel to itself and also parallel to the grinding line GL and grinding wheel spindle axis. The axis of the sleeve 61 as viewed in Figure 10 and hence the axis and ball end of the center CR may thus be given any desired path of movement, under controls later described, in repeated cycles, one cycle for each face F of the two diametrically opposed

11

blade members T, T (Figure 6) carried by the work-holder W.

In similar manner, a similar mounting for the shaft 60 (Figure 6) that carries the live center CL of the head stock control unit provides for movement of the ball-ended center CL and by controls later described that center is displaceable or movable in any desired path, also in repeated cycles synchronized with the cyclic movement of the right-hand center CR of the tail stock unit 53, with such dissimilarities in the two paths of movement of the centers, in each cycle, that the axis of the work-holder and of the blade or blades is universally tiltable and shiftable, as earlier above described. Accordingly frame housing 56 of the head stock control unit 52 also has, extending horizontally and rearwardly, just underneath its top cover plate 58, a horizontal link 92 constructed and pivotally mounted the same as the link 62 above described and pivotally supporting at its rear end a depending H-shaped link 93 substantially the same as the above-described link 63 with pivotal connections therebetween the same as earlier described; in Figure 6 are shown in section the bored-out axially spaced lower arms 93^e and 93^f of the pendent link 93, and in the bores thereof are mounted and secured bearing structures for rotatably supporting the shaft 60 and holding it against axial thrust, the supporting linkages insuring that the axis of shaft 60, when the latter is displaced, moves parallel to itself and is always maintained parallel to the interfitting guideways between the frame housing 56 and the table 42 and hence parallel to the grinding line GL of the grinding wheel as well as to the grinding wheel spindle axis, regardless of what position the head stock unit 52 is given lengthwise of the table 42.

The spaced bearing structures for the shaft 60 (Figure 6) comprise externally tapered bearing sleeves or bushings 94 and 95, each longitudinally slotted as at 94^a and 95^a, respectively received within sleeve elements 96 and 97 which are internally tapered and relative to which the slit bearing bushings 94 and 95 may be drawn axially, to the left in Figure 6, to contract them, by the respective nuts 98 and 99 threaded onto the external threaded portions of the bearing bushings 94 and 95, respectively, and bearing against the respective left ends of the sleeves 96 and 97; in this manner play and wear may be compensated for and the desired axial relation of the shaft 60 consistently maintained.

Axial thrust to the left is taken up by a suitable thrust bearing which may comprise a ring-shaped bearing plate 101 secured, as by pins, to the right-hand end of the bearing sleeve element 96 and coacting with a thrust collar 102 splined to the shaft 60, as at 103, and adjustably positionable along the shaft, as by set screw 104, the left end of collar 102 being provided with a ring-shaped member 105 of good bearing material for bearing engagement with the bearing face of the stationary thrust plate 101. This construction permits initial determination of the axial position of the shaft 60 in its axially spaced bearings and also provides for takeup of play or wear between the thrust bearing elements. Axial displacement of the shaft 60 to the right is prevented by a collar 107 which bears against the left end of the split bearing bushing 95, being set in position by a set screw 108 after setting of the thrust bearing structure 101—102. The right end of the bearing structure 95—97 is closed off by a ring plate

12

110 secured to the part 97 and provided with an oil retaining ring 111 as shown.

Provision is made for driving connection, always in fixed and invariable relation, between the shaft 60 and the work-holder W, bearing in mind that the blade element or elements T, T are assembled to the work-holder always with the blade surface to be ground in fixed relation to the work-holder, because of the synchronization, 10 with the rotary movement of the work-holder, of the independent but related controls for shifting the two supporting centers CL and CR. Such connection conveniently comprises a collar 113 (Figure 6) splined or keyed to shaft 60, as at 114, 15 and removably secured to the shaft by set screw 115, the splined or keyed connection 114 thus fixing the position of a dog which comprises a shank 116 projecting from and axially adjustably secured in a cylindrical bore or recess in the collar 113 and terminating in a ball end 117 (see also Figure 13) that is receivable in a slot 118 (Figure 14) in the left end of the arbor or work-holder W and tangentially engageable at diametrically opposite points in the ball end 117 by the inner ends 20 of two screws 120 and 121 (Figure 14). These screws are carried in axially aligned threaded holes in the opposed walls of the slot 118 which is wider than the diameter of the ball end 117 so that by adjustably positioning the two screws to 25 clamp the ball end 117 between their inner ends, the desired angular relationship of the work-holder W and blade or blades carried thereby to other control parts synchronized with the rotary movement of the work-holder may be obtained. 30 For speed and facility in the removal and replacement of the work-holder W, of which any suitable number of identical ones to carry identical and identically positioned blade members T may be employed successively in the machine, each such 35 work-holder has one of its screws, such as the screw 120, provided with a lock nut 122 to lock its inner ball dog-engaging end in the selected position once and for all while the other screw 121, which may have a finer thread, is provided 40 with a knurled head 123 for quick and easy manual control to bring it into engagement with the diametrically opposite point in the ball-ended dog or when a work-holder is mounted in position and to quickly disengage it therefrom. 45 50 when the work-holder is to be removed for replacement by another in which blades to be ground are already secured in fixed relationships as above described.

The inner ends of the screws 120, 121 provide 55 flat parallel faces of substantial area so that dog-driving connection with the work-holder W is always maintained without play or back-lash even though the axis of work-holder W is thrown out of coincidence with the axis of the driving or 60 live center CL at varying angles in all planes, as the two ball-ended centers 54, 55 partake of relative universal displacements as above mentioned and under the controls later described.

In effect under these controls and according to 65 the characteristics of the straight line faired surface to be ground, the work-holder W and its axis as determined by the center-engaging journal boxes JL and JR (Figure 6) and with which axis the blade axes are coincident, may be said to 70 "wobble," its ends partaking of different degrees and directions of movement according as the supporting centers CL and CR are controllably displaced. As a result the projected distance between the bearing surfaces of the journal boxes JL and JR becomes less as the departure from co-

axiality of the supporting ball centers 54 and 55 becomes greater. Accordingly provision is made for automatically adjusting the spacing between the ball centers 54 and 55 in a general axial direction to this change in distance, and this is preferably accomplished by causing the dead center CR in the tail stock control unit to axially move or follow up a lessening of that distance and to axially recede when that distance increases. As above described, center CR is fixedly carried in sleeve 61 which is slidable in the frame sleeve 87, there being provided two axially spaced bearings 127 and 128 (Figure 6) fixed within the ends of the stationary sleeve 87 and slidably supporting the inner sleeve 61 at its extreme ends. Since center CR need not rotate, a splined connection 138 is provided between the two sleeves. At its right-hand end sleeve 61 is counterbored to receive a helical spring 131 whose outer end bears against a fixed part secured, for example, to the outer end of the bored-out arm 63 of the pendent link 63. Spring 131 is normally under compression and exerts a continuous but yieldable force urging the sleeve 61 and center CR to the left in Figure 6 and hence in the general direction toward the opposed center CL; thereby the two centers CL and CR are self-accommodating to whatever changes in their spacing is necessitated by the angular shifts of the work-holder W relative thereto, and the arbor W and its blade or blades T are assured of dependable rotative support throughout their "wobble."

Drive shaft 60 of the head stock control unit and hence the work-holder W are rotated at a relatively low angular velocity, on the order of 20 R. P. M., and in the preferred embodiment are driven at a constant angular velocity, in which case the controls for the relative universal shifts or displacements of the centers CL and CR, synchronized with the rotary movement and physical displacement of the blade to be ground, are more conveniently correlated increment by increment of angular rotary movement of the blade. The drive of shaft 60 and live center CL and the drive of the shaft controls in the head stock and tail stock units are preferably effected by the provision of the drive head or power unit 51 earlier above mentioned and better shown in Figures 1, 7, and 8, which is constructed to be mounted upon and secured to the bed or table 42 in the same manner as are the units 52 and 53, as was described above in connection with Figure 10, the clamping elements 45-46 for the power unit 51 being shown in Figure 8; thereby the power unit is adjustably positionable and quickly alignable with the other units.

Drive head 51 may comprise a built-up housing-like base frame 135 which may be given a flat top to support an electric motor 136 (Figures 1 and 8) and a reduction gear unit 137 which is driven from the motor 136 by pulleys and drive belts indicated at 138; reduction gear unit 137 may be of any suitable construction and may be provided with any suitable means for changing the reduction ratio so as to provide for a suitable range of selectability of speeds of drive of the correlated live center drive and control devices in the head stock and tail stock control units.

The low-speed output shaft of the reduction gear unit 137 emerges at the left-hand end (Figure 1) and is shown at 139 in Figure 8, and from that low-speed shaft driving connections are provided to drive two jack shafts 141 and 142 which are rotatably supported in parallel relation in the lower part of the housing frame 135 (Figures

7 and 8) and of which shaft 141 is so supported and located that its axis is more or less in line with the axis of shaft 60 of the head stock unit (Figure 2), while shaft 142 is located forwardly of shaft 141. Shafts 141 and 142 may be mounted and supported in any suitable bearing structures in the base frame 135, illustratively by combined radial and thrust anti-friction bearings indicated at 143 in Figure 7. The left ends of the two shafts overhang the end of the housing frame, as does the reduction gear shaft 139, and by these overhanging ends the three shafts are suitably geared together as, for example, by means of gears or pinions 144, 145, and 146, and a toothed belt or toothed chain 147 which is preferably provided with a takeup or idler roller or pulley 148 which is eccentrically carried in a bracket part 150 of a plate-like support 151 which is carried, coaxially with the shaft 139 (Figure 8), by the vertical end wall of the gear unit 137, being rotatively adjustable and locked in adjusted position by clamping screws 152 passing through arcuate slots 153, whereby slack and back-lash in the belt or chain and its gears may be eliminated and the driving connection and relationship between jack shafts 141 and 142 maintained invariable. Furthermore, for reasons later pointed out, jack shaft 142, from which certain controls are to be driven, makes two revolutions for each revolution of jack shaft 141 from which the live center CL is to be driven, and in the illustrative drive this ratio is achieved by making the gear 145 of twice the pitch diameter of gear 146.

Jack shaft 141 of the drive head 52 is connected at its left end (Figure 7) to the right end of head stock shaft 60 in a manner to permit freedom of substantial shift, in all directions, of the shaft 60 parallel to itself and without affecting constancy of angular velocity of shaft 60 as the latter is displaced from coaxiality with the jack shaft 141. For this purpose I provide an intermediate shaft 156 which is coupled at its ends to the ends of shafts 141 and 60 by universal couplings 157 and 158 which may be of any suitable or known construction and interrelationship to maintain identity or constancy of the angular velocities of the driving and driven shafts even though the displacements therebetween effect angularities between each and the intermediate shaft 156. Coupling 158 may be secured to shaft 60 (Figure 6), as by interfitting it with a hub member 160 on shaft 60, being secured thereto as by screws 161; in similar manner the other coupling 157 (Figure 7) may be secured, as by screws 162, to a hub member 163 on the end of jack shaft 141. These hub members are keyed to their respective shafts and the entire coupling between the two is devoid of play or back-lash. Keyed hub member 163 is provided with an axially extending slot 164 and the rear wall of the base frame 135 has a rearwardly projecting horizontally slotted lug or bracket 165 in the slot of which is neatly fitted, and pivoted by pin 166, an L-shaped arm or key 167 whose free end, when the key is swung into the position shown in Figure 7, neatly enters the slot 164 in hub 163 and locks the parts, including jack shaft 141 and head stock shaft 60, in a corresponding position against rotation, a position with respect to which other parts may be adjusted or set, in initially setting up the machine for a particular blade-grinding job.

Projecting forwardly from the front wall of housing frame is a similar horizontally slotted lug 168 in which an L-shaped arm 170 is similar-

ly pivotally mounted, which arm when swung into the position shown in Figure 7 neatly fits into a slot in a collar 171 clamped, adjustably by bolts 172, to the right end of jack shaft 142, whereby for setting-up purposes the rotary position of the jack shaft and control parts driven thereby may be fixed relative to the jack shaft 141 and the head stock shaft 60.

Referring now to Figure 6, head stock control unit 52 and tail stock control unit 53 are respectively provided with horizontal and coaxially aligned jack shafts 175 and 176 carried in suitable anti-friction bearings 177, 178 for jack shaft 175 and 178, 179 for jack shaft 176, in turn carried and mounted in the respective end walls of the respective housing frames 56 and 57. The adjacent ends of jack shafts 175 and 176 are coupled together by a telescoping coupling structure generally indicated at 180 to maintain driving connection throughout various longitudinal or axial spacings between the units 52 and 53 lengthwise of the bed or table 42 and constructed, as is later described, to permit rotary adjustment of one shaft relative to the other. The left end of jack shaft 175 (Figures 6 and 7), which is in alignment with the right end of drive unit jack shaft 142, is detachably coupled thereto by a slit sleeve coupling 182 provided with clamping screws or bolts 183 and with splined or keyed connections with both shafts 142 and 175, as indicated in broken lines.

The left end wall of housing frame 56 of head stock unit 52 (Figure 6) is bored out and constructed to form a seat for the outer race of an anti-friction bearing 185, the inner race of which is secured to one end of a control cam shaft 186 adjacent the other end of which shaft 186 carries and has clamped thereto the inner races of anti-friction bearings 187 whose outer races are fitted into and suitably secured in the bore of a large heavy boss 188 that is integrally formed with the bottom of the housing frame 56 and projects upwardly therefrom. Jack shaft 175 and cam shaft 186 are geared together by gears 191 and 192 of 1:1 ratio, the gears being non-rotatively fixed to their respective shafts, as by taper pins 193 preferably threaded at their small ends and provided with draw nuts as indicated. The right end of cam shaft 186 closely adjacent the heavy bearing support 187-188 has secured to it a control cam unit, generally indicated by the reference character 196, which is to coact with and control the displacements of the horizontal link 92 and the pendent link 93 supporting the live center shaft 60; it comprises two cams LV and LH which, as later described, coact with other parts to determine, respectively, the vertical and horizontal components of displacement of the ball-ended center CL per unit angle of rotary movement of that center and the workholder W.

Tail stock control unit 52 is similarly provided with a cam shaft and cam unit, being in general constructed right-handed in relation to the left-handed construction just above described. The right end wall of housing frame 57 (Figure 6) is bored out to support the outer races of an anti-friction bearing 198, the inner race of which is secured on the right end of cam shaft 200, as shown, and near its right end cam shaft 200 extends through and has secured thereto the inner races of anti-friction bearings 201 whose outer races are fitted into and suitably secured in a large bore of a heavy boss 202 integrally formed with the bottom wall of the housing frame 57,

and upstanding therefrom, as is also shown in Figure 10, and on the inner end of cam shaft 200, adjacent the just-described bearing support 201-202, is secured the cam unit generally indicated by the reference character 203 and comprising two cams RV and RH which coact with other parts to give the ball-ended center CR respective vertical and horizontal components of displacement or movement per unit angle of rotary movement of the work-holder W and the blade or blades carried thereby. Cam shaft 200 is driven from jack shaft 176 by gears 204 and 205 of 1:1 ratio and respectively pinned to the shafts by taper pins 206 with draw nuts on their smaller ends as shown.

The vertical-component cams LV and RV of the two units, by the just-described constructions, will be seen to be positioned just underneath the respective horizontal links 92 and 62 and each in a vertical plane that is substantially midway between the end bearing supports, such as the bearings 71-72 of Figure 9, by which the horizontal links are pivoted, and each of the latter, at that substantially vertical plane and just above the axes of the respectively underlying cam shafts, is provided with a cam follower, preferably in the form of a roller R, to ride along the peripheral cam face as the cam rotates. In Figures 10 and 11 the construction and mounting of this roller R is shown in detail for the horizontal link 62, and a description thereof will suffice for both. Thus the horizontal link has depending from it an integrally formed boss 207 which is provided with an arcuate recess or bore 208, the axis of curvature of which is parallel to the axis of the underlying cam shaft, the depending boss 207 being centrally slotted, as at 210, in line with the underlying cam RV and to a width greater than the thickness of that cam. There are thus formed two axially spaced seats of more than 180 degrees in extent, being open at their lower ends throughout less than 180 degrees, for the reception of the outer races of two axially spaced anti-friction bearings 211 and 212 whose inner races are fitted onto the stud-like shaft extensions 213 and 214 of the roller R with which they are coaxial. Securing plates 215, secured to the boss 207 by screws 216, hold the bearing and roller assembly against shifting axially relative to the boss 207 and the horizontal link from which it depends. The vertical-component cam can thus enter between the spaced bearing members to engage the roller R which is held thereagainst by the weight of the heavy cross-link (62 or 92) and of the parts pivotally carried by it at its free end.

In this manner and by appropriately shaping the left vertical-component cam LV in relation to the peripheral shape of the right-hand vertical-component cam RV, the horizontal links 92 and 62 of the two control units may be swung in up-and-down direction (see Figure 10) in such related degrees and/or rates as necessary to tilt the axis of the work-holder and of a blade being ground, in a vertical plane as viewed in Figure 1 to present any particular line-like portion of the blade surface in the same horizontal plane of the horizontal grinding line GL of the grinding wheel.

Whil such actions are taking place the centers CL and CR can be given horizontal components of displacement so as to provide any desired departure from parallelism between the axis of the workholder W and the grinding line GL as viewed in Figure 6, by controlling inde-

pendently of each other in any desired corelation the displacements in horizontal directions of the pendent links 93 and 63 about the respective axes of their pivotal supports from the horizontal links 92 and 62, by the respective actions of the horizontal-component cam LH in the head stock control unit 52 and of the horizontal-component cam RH of the tail stock control unit 63 on cam followers or rollers 220 and 221 carried respectively by the shaft 60 and the sleeve 87 (Figure 6). These roller or cam followers 220 and 221 are rotatably mounted on shaft 60 and sleeve 87 by anti-friction bearings 222 and 223, respectively, the inner races abutting against suitable shoulders against which they are clamped and secured by nuts 224 and 225, respectively.

The inner ends of two axially spaced springs 226 and 227 are anchored to the lower ends of the arms 93^e and 93^f of the pendent link 93 (Figure 6) and at their forward ends are secured by links 228 to the front wall of the housing frame 56; they are under tension to yieldingly bias the lower end of the pendent link 93 toward the front of the housing frame and thus always maintain the cam follower roller 220 of shaft 60 in engagement with the cam LH.

In like manner two axially spaced springs 230 and 231 have their rear ends secured to the lower arms 63^e and 63^f of the H-shaped pendent link 63 with their forward ends anchored by links 228 to the front wall of the housing frame 57, being tensioned to yieldingly maintain the roller 221 in peripheral engagement with the cam RH. The relationship of these parts is better shown in the transverse section of Figure 10.

Cam units 196 and 203 (Figure 6) are driven in unison, jack shafts 175 and 176 being connected together by the coupling 180; they make one complete revolution for each half-turn of head stock shaft 60 and the work-holder W where the latter is constructed, as in the illustrative embodiment, to support two blade members T, T in precise juxtaposition to each other and with their axes O—X coincident with the axis of the work-holder W, whereby an exact 180 degrees of rotation is allocated to each blade member T during which its blade surface F is shaped (Figure 3). During each such half-turn the cam units 196 and 203 convey to the work-holder W the necessary "wobble" by giving the ball-ended centers CL and CR the needed interrelated horizontal and vertical components of displacement which have to vary and change or differ at the two ends of the work-holder axis and in such sequences as is necessary to present successive straight-line portions of the blade B always and only to the horizontal grinding line GL of the grinding wheel 22. Accordingly the contour of the left vertical-component cam LV differs from the contour of the right-hand vertical-component cam RV, and in the same manner the horizontal-component cams LH and RH differ in contour. Companion left and right end cams may have portions geometrically equal or geometrically similar; in the former case the corresponding portion of the blade surface F would be straight line faired with the elements parallel to the axis O—X (Figure 3), and in the latter case a corresponding portion of the blade surface F would be cut or shaped or ground, also straight line faired, but with the straight line elements divergent and not parallel to the axis O—X. Other portions of the cam peripheries or contours may have curvatures which geometrically are neither equal

nor similar, and that may be true throughout the entire effective control portions of all of the cams, according to the straight line faired conformation desired for the blade surface F. Any desired similarities or dissimilarities, according to need, may be provided in or throughout various companion portions of the right and left cams that control the physical displacement of the centers CL and CR; for example, one of the centers may, throughout the desired portion of the rotation of the blade, partake of displacement only horizontally or only vertically or remain stationary, while the other center is shifted or displaced by its control cams. By way of further example, a portion of the blade face may have to be cylindrical and of the same radius to the axis O—X throughout, and in such case corresponding portions of the control cams for the two centers are given shapes to hold the two centers against displacement throughout the desired angle of rotation of the blade. Thus a wide range of straight line faired curvatures may be cut or ground into the blade surfaces according to whatever relative characteristics of shape or curvature are given the lines G and H (Figures 3, 4, and 5) along which, as earlier described, the ends of the generating straight line move. Also, it will now be apparent that, within limitations, the grinding wheel 22 may have its surface shaped or curved, for example, slightly convex, so that the grinding line GL departs from straight-line relation whereby blade faces may be shaped having the peculiarities or characteristics in relation to the blade axis as above described excepting that instead of being straight line faired, they are faired according to the curved or other shape given the grinding line GL; in such case the grinding wheel is not axially reciprocated.

In Figures 16 and 17 are diagrammatically shown relationships of the parts respectively at the commencement of grinding at the leading edge 20 (Figure 3) and the termination of grinding at the trailing edge 21, the parts being schematically shown as they would be seen from the left in Figure 6. Referring first to Figure 16, and assuming that the straight line terminus of the face F adjacent the leading edge 20 is to be parallel to the axis O—X (Figures 3, 4, and 5), to present that terminus to the straight grinding line GL, the coincident axis O—X of the work-holder W and blade or blades T has to be dropped below the horizontal plane H—P in which the grinding line GL lies and accordingly the vertical-component cams LV and RV have portions of equal radius engaged by the two rollers R of the horizontal links 62 and 92 dimensioned to lower both ends of the axis O—X below the horizontal plane H—P to the appropriate extent. Because of that equality at these starting points the rollers R, R and the two horizontal links 62 and 92 appear coincident in Figure 16, as do the corresponding equal portions of the two cams. Correspondingly the horizontal-component cams LH and RH, where they engage the rollers 220 and 211 respectively, have portions of equal radius to displace centers CL and CR horizontally to the same extent to just bring the above-mentioned surface terminus at the leading edge 20 into coincidence with the grinding line GL; as indicated in Figure 16, that is a displacement to the left of the vertical plane V—P through the pivotal connections of the pendent links to their respective horizontal links. Because of that equality of radius and of horizontal displacement of both ends of the axis O—X, the pendent arms 63 and

93 and their respective rollers 220 and 221 appear coincident in Figure 16.

Were the straight line terminus of face F adjacent the leading edge 20 to be not parallel to the axis O—X (Figures 3, 4, and 5), that terminus would be brought into coincidence with the straight grinding line GL of the grinding wheel, at the above-mentioned starting points of the cams, by providing the required inequality of radii, at the starting points, in the companion vertical-component cams LV and RV or in the horizontal-component cams LH and RH, or both, according as the out-of-parallelism is only in horizontal projection as viewed in Figure 3 or is only in vertical projection as viewed in Figure 3, or is in both horizontal and vertical projection.

As the work-holder W slowly rotates counter-clockwise (Figure 16), successive companion portions of the horizontal-component cams and of the vertical-component cams shift the respective supporting centers CL and CR (Figure 6) and hence the ends of the work-holder axis in correlation to each other but mechanically independently of each other, giving the axis O—X about which the work-holder W and blade T is swung the necessary displacement or wobble to present successive linear portions of the blade face F to the horizontal grinding line GL, always without material or detrimental engagement with the grinding wheel surface above or below the grinding line GL, until the straight line terminus at the trailing edge 21 of the face F (Figure 3) is reached. In the earlier stages of the rotary movement of the work-holder and blade, commencing at the leading edge 20 (Figures 3, 4, and 5), the companion vertical-component cams LV and RV shift the two supporting centers so that the axis O—X is below the horizontal plane H—P through the grinding line GL (Figure 16), while at the same time the horizontal-component cams LH and RH shift the axis ends in correlation, but because of the peculiar shape of the blade, during the later stages of this rotary movement, the vertical-component cams LV and RV shift the centers CL and CR to bring the axis O—X of work-holder and blade above the horizontal plane H—P as indicated in Figure 17, where the parts are shown with the end terminus of face F at the trailing edge 21 of the blade exactly at the grinding line GL. Because that end terminus of the face F is not parallel to the axis O—X either in vertical or horizontal projection as viewed in Figures 3, 4, and 5, the two horizontal links 62 and 92 which determine the vertical displacement of the two supporting centers do not appear in coincidence nor do the pendent links or arms 63 and 93 by which the horizontal displacement of the supporting centers and the ends of the axis is effected. At this position of the parts where the end terminus of the face at the trailing edge 21 is being ground, the axis O—X appears in Figure 17 tilted to both the horizontal plane H—P and the vertical plane V—P in order to bring the straight line terminus of face F at the trailing edge 21 into coincidence with the straight horizontal grinding line GL of the grinding wheel; Figure 17 thus illustrates three-dimensionally though schematically one position of wobble of the work-holder and blade axis O—X, happening to be a position at the conclusion of the cutting or grinding operation.

In between the commencement of the grinding adjacent the leading edge 20 and the conclusion of grinding at the trailing edge 21, the axis O—X

may at times be parallel to the grinding line GL and at other times may partake of angularities, of which one is illustrated in Figure 17, according to the contour required for the blade face F; the angularity of the axis O—X relative to the grinding line GL may be at times only in horizontal projection, at other times only in vertical projection, and at other times in both vertical and horizontal projection as viewed in Figures 3, 4, and 5. With the illustrative shape of blade shown in the latter figures, the axis O—X, while bodily shifted horizontally and vertically, is maintained parallel to the grinding line GL throughout the geometrically equally conformed full-line portions of the cams LV—RV and LH—RH as seen in Figure 16, to grind the earlier above-described portion F¹ (Figures 4 and 5) of the face F and thereafter the axis O—X, while physically displaced horizontally and vertically, as needed, is shifted angularly (made to "wobble") with respect to the grinding line GL under the control of the non-coincident and differently contoured portions shown in full lines and broken lines of the cams LV and RV, respectively, and of the cams LH and RH, respectively, in Figures 16 and 17 for effecting the shaping of the portion F² of the face F as seen in Figures 4 and 5. The transition from one type of shift to the other takes care also of the difference in the angles x and x¹ above described in connection with Figures 4 and 5.

The face of the blade B is thus steadily and progressively presented element by element always to the horizontal grinding line GL, throughout whatever shift, parallel or angular, is given the blade B and its axis O—X vertically and horizontally; at each successive increment of rotary movement or translation of the blade surface relative to the grinding line GL, the grinding wheel cuts the blade face always in a straight line, the succession of straight lines thus cut, for the successive increments of rotary movement and corresponding increments of shift of the same or different magnitude or direction at the respective ends of the axis O—X, merging side by side into each other. The resultant surface F is smoothly shaped and is curved to the desired contour and, with the grinding line GL straight-lined, the resultant contoured face F of the blade is straight line faired.

The work-holder W continues to rotate, as do the two cam units 196 and 203, the work-holder rotating to finish out the 180 degrees of rotary movement allocated to it for the grinding of one blade B and the two cam units to finish out the 360 degrees of rotary movement thereof allocated to the 180-degree turn of the work-holder W; the completion of that 180-degree turn of the work-holder W finds the two blades B, B vertically juxtaposed to each other, the already ground blade B being at a 6-o'clock position and the other blade B carried by the work-holder W being at a 12-o'clock position, as viewed in Figures 16 and 17, with the ball-ended universally-acting driving dog 117 (Figures 6, 13, and 14) at the 6-o'clock position. From these positions the parts, continuing to rotate, commence a second cycle during which the work-holder W rotates 180 degrees and the two cam units 196 and 203 rotate 360 degrees to effect the controls and shifts or "wobble" above described but now in relation to the other blade carried by the work-holder, the face F of which is contoured as above described, and with its axis coincident with the axis of the already ground blade B, the contoured

face of the latter is exactly duplicated in the former.

As shown in Figures 16 and 17, the respective cams of the two cam units 196 and 203 have conformations which during the rotary transition of the work-holder from the position shown in Figure 17, were the trailing end terminus of face F is being cut or ground, to a position to present the leading edge terminus 20 of the face of the other blade B to the grinding line GL, shift the axis O—X and the work-holder away from the grinding line and downwardly; this transitory shift from one cycle to the next not only takes care that the leading edge portion of the succeeding blade is properly presented to the grinding line GL, but also takes care that the body portion of the work-holder W intervening the two blades supported by it is prevented from contacting the grinding wheel.

When the face of the second blade B has been ground and the second blade assumes a 6 o'clock position (in Figures 16 and 17), the ball-ended driving dog 117 is at the 12 o'clock position, with the manual screw 123 that coacts with it (Figure 14) passing toward the front of the machine. At this point, the grinding wheel and its slide 31 having been retracted rearwardly (Figure 6), the drive of the head stock and tail stock control units is halted and the operator loosens the screw 123 with which the driving dog universally coacts, thus to ready the work-holder W with its two ground blades for removal from the machine. The work-holder is removed by axially displacing the center CR (Figure 6) to the right against the action of the spring 131 and with the resultant increase in distance between the two centers CL and CR, the work-holder with the ground blades is removed and another work-holder with two blades therein to be ground is substituted on the centers for it, driving dog 117 entering the work-holder slot 118 to engage the lock screw 120 (Figure 14) whence the operator turns the screw 123 to engage the ball-ended dog 118 to take up play between itself and the companion screw 120.

While the center CR may be axially displaced to the right in Figure 6, by manually opposing the spring 131 for purposes of mounting or dismounting the work-holder, spring 131 is relatively powerful in order that it dependably follow up toward the live center CL during wobble of the work-holder, and accordingly it is preferred to provide power-actuated means for retracting the center CR. This preferably comprises hydraulic means in the form of a cylinder 236, as shown in Figure 6, mounted and secured to the arm 63^f of the pendent link 63 in coaxial relation with the frame sleeve 87 carried by the link and the sliding sleeve 61 that carries center CR. One end wall of cylinder 236 is provided with an aperture and sealing ring 237 for the passage therethrough of a piston rod in the form of a stepped or shouldered tubular member 238; about its smaller-dia metered right-hand end (Figure 6) and abutting against the shoulder therein, hollow piston rod 238 carries a piston generally indicated by the reference character 240, comprising a collar, two washers between which a leather or other yieldable piston ring is peripherally clamped, all clamped against the piston rod shouldered by a nut 241 threaded onto the outer end of the hollow piston rod 238. The other end of the latter passes through the helical spring 131 and is threaded, as at 242, into the bore of the slidable sleeve 61. A washer 244 extends

about the hollow piston rod 238 and bears against the yieldable sealing ring 237 against which it is held by one end of the spring 131. As the latter acts upon the slidable sleeve 61 and center CR as above described, piston 240 and piston rod 238 slide freely relative to the cylinder and sealing ring. However, upon supplying the cylinder chamber to the left of the piston 240 with fluid under pressure, preferably a liquid, the piston and sleeve and center are thereby moved toward the right in opposition to spring 131 and may be held so displaced until the pressure fluid is released from the cylinder. Cylinder 236 is provided with a port channel 245 which mates with a channel in the cylinder head 246 to which a flexible pipe or conduit 247 may be connected to supply the cylinder chamber with fluid under pressure and to release the same from the cylinder, through a suitable two-way valve 248 connected, respectively, to a fluid supply line 250 and exhaust line 251. Valve 248 is preferably manually operated from the front of the machine as, for example, by a hand lever 252 (Figure 1) so that the operator can set valve 248 in one position to connect cylinder to supply line 250 and thereby withdraw center CR and hold it withdrawn, while he removes and replaces the work-holder and then set valve 248 in its other position to connect the cylinder to the exhaust line 251 to let spring 131 enter the center CR in the journal box JR of the work-holder and thereafter let the spring follow up changes in the projected distance between the centers CL and CR as the work-holder W wobbles.

The just-described construction for hydraulically controlling the center CR achieves other advantages. Desirably, under some circumstances, center CR (Figure 6) and sleeve 61 are permitted to rotate to eliminate friction and wear at the ball end 55 of center CR and journal box JR, the rotation being slow and being effected in response to the slow rotary movement of the journal box JR itself; in such case the key may be omitted from the splined connection 130 earlier above mentioned, whereupon sleeve 61 is not only slidable but also rotatable relative to the spaced bearings 121, 128.

Drainage of liquid that might leak or emerge from cylinder 236 at the sealing ring 237 is easily effected by a channel 253 that connects with the interior of sleeve arm 63^f and extends in the wall of cylinder 236, leading at its right-hand end to a mating channel and pipe connection 254 in the cylinder head 246.

Cylinder head 246 has an opening 255 aligned with the axis of the hollow piston rod 238 so that a rod may be slid therethrough for dislodging the taper center CR from its taper seat in the sleeve 61, when it is necessary to replace the center, for example, with a differently dimensioned one. Live center CL in the head stock may be dislodged from its taper seat in the shaft 60 by means of a nut 256 threaded onto its outer end and which when turned to bear against the end of shaft 60, acts to unseat and withdraw the center CL.

Provision is made for facility and flexibility of inter-relationship of the various parts to facilitate speedy initial setting up of the apparatus, as well as speedy readjustment during operation where necessary, to achieve the intended wobble control of the axis of the work-holder W and the blade member or members T carried by it, bearing in mind that left-hand vertical-component cam LV and right-hand vertical-component cam RV have different contours and that the same is

true of the two horizontal-component cams LH and RH; moreover, cam dimensions and the just-mentioned contours may in turn vary considerably according as it is required to grind differentially dimensioned or contoured blade faces under controlled conditions of wobble of work-holder and blade members relative to the fixed grinding line GL. All four cams bear the proper relation one to the other, and if that relationship is established for any selected point in a single grinding cycle, it remains proper and so established for all other points in the cycle.

Accordingly the two cams LV and LH (Figure 6) of cam unit 196 of the head stock control unit 52 can be and are constructed as separate cams, each with its particular contour to give, respectively, the required vertical-components of displacement and horizontal components; preferably they are made to be capable of relative rotary adjustment to fix their relation to one another, a relation which, because of the 90-degree displacement of their respective roller followers, should also be a 90-degree displacement between them. Thus cam LH on cam unit 196 has a sleeve-like hub 260 which is internally tapered to fit onto the tapered end of shaft 186 to which it is splined or keyed as at 262. Hub 260 is externally cylindrical to receive thereon cam LV and its sleeve-like hub 261 with a face of cam LV abutting against the end of hub 260 of cam LH. Cam LV has a number of arcuate slots through which extend screws 263 that are threaded into hub 260 whereby cam LV may be rotatively adjusted relative to cam LH to give the desired 90-degree displacement and then secured by tightening the screws 263. Graduations, indicated in Figure 6, on hub 261 may be used to facilitate setting. The resultant cam unit is clamped to cam shaft 186 by clamping plate 265 and clamping screw 266 threaded into the shaft and it may be so secured in any selected rotative relation to the shaft itself, without disturbing the relation between the two cams LV and LH.

The two right-hand cams RH and RV of the tail stock control unit are also constructed as individual cams and respectively appropriately contoured, but are assembled to each other in a manner to permit setting of one about the axis of the other. Thus horizontal-component cam RH has an internally tapered hub 270 to fit onto the tapered end of cam shaft 200 (Figure 6) and provided with a keyway as shown to coat with a key 272 in the cam shaft whereby the cam is assembled to the cam shaft 200 in fixed relation; the hub 270 is externally cylindrical to receive the vertical-component cam RV and its hub 271 which terminates against a face of cam RH to which it is secured by clamping screws 273 (Figures 6 and 10), illustratively four in number, which pass through arcuate slots 274 in cam RH, whereby cam RV is rotatively adjustable relative to cam RH throughout a suitable range in either direction from a true 90-degree displacement between the start-grinding points of the two cams. As indicated in Figure 6, hub 271 on adjustable cam RV may bear graduations or other indicia relative to a marked point or datum line on the face of cam RH to indicate direction and extent of departure from the just-stated 90-degree relation. The resultant two-cam unit 203 is clamped to cam shaft 200 by clamping plate 275 and clamping screw 276 threaded into the tapered end of shaft 200.

As seen in Figure 6, each cam shaft 186 and 200 has a brake drum 277, 278 and each has

thereabout a suitably lined adjustable brake band 280 comprising in effect a split metal band having its ends adjustably secured together by an adjusting screw 281 (Figure 10) and provided with an arm 282 that abuts against the bottom wall of the housing frame. These brakes impose a drag or load on the two cam shafts the magnitude of which is adjustable by appropriately setting the adjusting screws 281 and thereby back-lash and play in the drives to the respective cams is always taken up and is prevented from causing divergence in back-lash or play from throwing the two cam units 196 and 203 out of synchronism; they can also aid in initially setting the cam units in relation to each other.

With cam unit 196 at the left, fixed to cam shaft 186 and the relationship between the two cams LV and LH fixed by assembly of the two as above described, and with cam RH at the right secured in fixed relation to the cam shaft 200, the desired synchronization of cams RH and RV in relation to cams LH and LV may be readily accomplished by the above-described structural features. The jack shafts 175 and 176 are coupled together by a coupling generally mentioned above and identified at 180 in Figure 6; it is constructed to permit rotative or angular shift of one jack shaft relative to the other for cam adjustment or synchronization and may comprise a sleeve 290 keyed and secured to the right end of jack shaft 175 to receive in its outer end a companion sleeve 291 in which the left end 176a of jack shaft 176 is telescopically received, the jack shaft portion 176a and the aperture in sleeve 291 being of any suitable non-circular cross-section so that they cannot rotate relatively to each other and hence sleeve 291 can drive jack shaft 176—176a. The telescopic relation between sleeve 291 and jack shaft part 176a permits maintenance of the driving connection for different axial spacings of the head stock and tail stock units 52, 53 lengthwise of the machine table 42.

The two sleeves 290, 291 are constructed for relative adjustment of the one about the axis of the other, and this means may comprise two opposed aligned screws 292, 293 threaded into two opposed holes in the sleeve 290 and that extend along a chord so that their inner ends project in spaced relation into the cylindrical interior of the sleeve 290; internal sleeve 291 is cut away or recessed on opposite sides to receive the inner ends of these screws and to leave a portion extending between the screw ends, forming in effect a radially projecting lug or lever arm which is clamped between the screws 292, 293. By this means interior sleeve 291 and hence jack shaft 176 may be adjustably positioned rotatively about the axis of sleeve 290 and jack shaft 175 within a suitable range or angle of adjustment, and thus cam shaft 200 in the tail stock control unit rotatively adjusted relative to cam shaft 186 in the head stock unit. With cam RH in the tail stock keyed to cam shaft 200, a corresponding adjustment thereof relative to cam LH on the cam shaft 186 can be effected to synchronize their settings and their respective control actions of their respective cam followers 221 and 220 so that the horizontal components of displacement at the respective ends of the work-holder W, whatever their similarities or differences, take place synchronously. Vertical-component cam RV in the tail stock, by means of the screws 273 and slots 274 in the fixed cam RH may be set in either direction about its axis and hence in relation to the setting of cam LV in the head

stock unit so that the two are set and act synchronously and so that the intended and desired vertical components of displacement of the two ends of the work-holder axis, whatever their similarities or differences, take place synchronously. Thus the parts may be readily set to achieve the required displacement or wobble of the axis of the work-holder and blade to give the latter its peculiar surface shape and readjustment facilitated.

For purposes of assembly and cam setting, provision is made for readily positioning and holding cam followers and related parts out of coacting relation with the respective cams. Thus each of the springs 226, 227 in the head stock (Figure 6) and springs 230, 231 in the tail stock may be quickly released so as to free the respective pendent arms 93 and 63 upon which they act. Each end link 228 is constructed as is better shown in Figure 10 and comprises two parts 228^a and 228^b of rectangular cross-section and hingedly connected together by a pin 284 whereby the outer part 228^b, provided at its outer end with a cross-bar handle 285, may be manually swung into or out of alignment with the part 228^a to which the spring end is hooked. The front wall of the housing frame has a hole 286 externally surrounded by a boss 287 against which the outer link part 228^b rests when swung at about 90 degrees to the inner link part 228^a, thus holding the spring under tension; but when outer link part 228^b is swung into alignment with inner link part 228^a, the now aligned links can slide together, to the left in Figure 10, along the hole 286 to an extent limited by the engagement of cross-bar handle 285 with the boss 287. Thereby the tension of the spring is relieved. In this manner either or both of the pendent arms 63 and 93 can be freed from the spring tension and cam follower rollers 220 and 221 (Figure 6) released from enforced engagement with their respective cams LH and RH.

Each of the horizontal links 62 and 63, with the above-mentioned spring released, may now be freely lifted up manually, cover plates 58 and 59 (Figure 1) of the head stock and tail stock units having been removed, thus to disengage the cam rollers R from their respective vertical-component cams RV and LV. These parts being relatively heavy, provision is made for facilitating raising them and for selectively positioning each in upwardly retracted position. The means employed to act on the horizontal links 62 and 92 are the same, and it will suffice to describe one of them in detail, as is better shown in Figures 9 and 10 with respect to the horizontal link 62. Its end remote from where it is pivoted has a bracket-like extension 296 cast or formed integrally with it and it is slotted, as at 297, to provide spaced arms between which is loosely received a square nut 298 (Figure 10). Nut 298 is mounted in the slot 297 for pivoting about an axis parallel to the axis about which the horizontal link itself can pivot at its forward end, as by two pins 300 that extend through the two spaced arms of bracket 296 with their inner ends entered into recesses in correspondingly opposed sides of the square nut, as is clear from Figure 9.

To the rear wall of the housing frame and just above the bracket extension 296 (see Figure 10) is secured an L-shaped bracket 302 which is bifurcated to provide two spaced arms between which is pivoted a block 303, by opposed pins 304 that extend through the arms and into opposed recesses in the block 303 with their coincident axes parallel to the axis of pivoting provided by

the pins 300 for the nut 298. When it is desired to retract either arm 62 or 92 upwardly, a cap screw 306 (Figure 10) is slid down through the hole 305 in frame-carried block 303 and then threaded into the threaded hole in the link-carried nut 298, the pivotal mountings of block 303 and nut 298 permitting these parts to be self-aligning under the action of screw 306 for this purpose as well as during the subsequent changes in angularity of the axis of screw 306 relative to the horizontal link itself as the latter is retracted upwardly. Upward retraction may be effected to any desired extent according to the extent of threading of screw 306 into nut 298; by using a wrench on the screw 306, such upward retraction of the horizontal link and the pendent link carried by it is accomplished with ease. Thus the cam follower roller R may be easily retracted from its position of coaction with the vertical-component cam in either the head stock unit or the tail stock unit, or both. The cam units 196 and 203 (Figure 6) are thus clear for replacement or adjustment.

Another aid in setting up the machine or in making adjustments comprises a dog arm 167 (Figure 7) by which head stock spindle 60 may be locked always in a single at-rest position, by swinging the dog arm 167 to enter the slot 164 (Figure 7) in the hub 163, thereby, in the illustrative embodiment, freezing the ball-ended spindle drive dog 167 and the work-holder W in the position shown in Figures 6 and 16 wherein that geometric element of one of the two blades B in the work-holder that corresponds to a surface line element through the vertical axes shown in Figures 4 and 5 is presented at the 9 o'clock position and in juxtaposition to the grinding wheel grinding line GL. With the parts thus frozen in position, left-hand cam unit 196 comprising cams LV and LH may be secured to cam shaft 186 (Figure 6) and right-hand cam unit 203 comprising cams RV and RH secured to cam shaft 200, by the respective keys 262 and 272; the key slots or locations in the cam shafts 186 and 200 and the keyways in the respective cams LH and RH are so located that, with the keys 262 and 272 aligned with each other or at the same o'clock position as viewed from one end of Figure 6, the cams LH and RH are correspondingly aligned and synchronized, a relationship which in turn is fixed by the geared connections of the cam shafts 186 and 200 to the respective jack shafts 175 and 176 and which can be precisely determined by appropriately setting the relationship between the telescoping coupling sleeves 290, 291 (Figure 6) as above described. With the toothed belt 147 (Figures 7 and 8) removed or disengaged from gear 145 or gear 146, or both, and with jack shaft 141 (Figure 7) locked by the lock arm 167, coupled together jack shafts 142, 175, and 176 may now be manually rotated to bring the cams LH and RH, either empirically or by appropriate markings on the cams, to a rotary position that gives the respective horizontal components of displacement appropriate for the above-mentioned 9 o'clock position of the above illustratively selected surface line element of the blade to be ground. With the illustrative form of blade B diagrammatically indicated in Figures 3, 4, and 5, it happens that, at that position, the pendent arms 63 and 93 are exactly vertical. Collar 171 on jack shaft 142 (Figure 7) is now set and clamped to shaft 142 in position to receive dog arm 170 which is swung into the slot of the collar, thus freezing the rotary position of the cou-

pled-together jack shafts and of the cam shafts and the cams LV and RV keyed thereto. The vertical-component cams LV and RV may now be rotatively adjusted and set relative to their respective and already fixed horizontal-component cams LH and RH, in the manner above described, to achieve the desired 90-degree displacements between companion vertical-component and horizontal-component cams; this may be done with the aid of indicia or the above-mentioned graduations, or empirically. The toothed belt 147 (Figure 8) is now replaced and the slack in it taken up by the idler 148, thus insuring the proper driving connection between the two jack shafts whereupon the dog arms 167 and 179 (Figure 7) are withdrawn to release the respective jack shafts for drive and operation of the apparatus. Here it is to be noted that should need arise, the apparatus may be halted at any time and the two drive unit jack shafts 141 and 142 dogged by the dog arms 167 and 179, respectively, thereby freezing all the parts in the same position in which they were initially set up and in relation to which any readjustment or replacement or checking may then be proceeded with.

The construction, action, and operation of the apparatus will be clear from the foregoing. The grinding wheel 22 is trued in any suitable manner to cylindrical form so that its grinding line GL is a straight line parallel to the grinding wheel spindle axis; a slight reciprocation axially of the grinding wheel spindle and hence of the grinding wheel itself, on the order of $\frac{1}{2}$ of an inch, is preferably effected as earlier above noted and any suitable reciprocating mechanism may be employed for that purpose, such as that shown in Patent No. 2,237,496. The grinding wheel 22 is carried, as above described, by the transversely movable wheel slide 31 (Figure 12) and the wheel slide may be controllably moved to bring it into and out of operative relation to the rotatable work-holder and to determine depth of cut, in any suitable manner and by any suitable means, illustratively by mechanisms shown in Figure 12, and it may be constructed and operated for manual and power or hydraulic movement in the manner described in the above-mentioned Silven Patent No. 2,522,485. For example, the feed screw 36 of Figure 12 may be manually rotated to move and position the wheel slide 31 and hence to move and position the grinding wheel 22 relative to the work in the work-holder W, by the hand wheel 41, as through gears 310 and 311, the latter being on the forward end of a shaft 312 which has a bearing 313 for its forward end; its rear or right-hand end (Figure 12) is keyed to one end of a sleeve 314 which telescopically receives shaft 315, being splined thereto as at 316, of the feed screw 36, bearing 37 forming a bearing support for both the right end of sleeve 314 and for the end of shaft 315. In this manner feed screw 36 may be manually rotated by the hand wheel 41. It may also be hydraulically rotated; thus the front of the machine base 23 carries a hydraulic cylinder 317 that extends lengthwise of the machine frame and in which is reciprocable a double-ended piston 318 having a rack 319 formed thereon intermediate of its ends to mesh with a gear 320 whose teeth extend through an opening in the side wall of cylinder 317, gear 320 being mounted on a shaft 321 that carries a gear 322 that meshes with the gear 311 on the feed screw shaft 312. Depending upon the direction in which the piston 318 is hydraulically moved, feed screw 36 is

thus rotated to feed the wheel slide 31 toward the work-holder or to move it away from the work-holder. Other details of such hydraulic actuation and control are disclosed in the above-mentioned Silven Patent No. 2,522,485.

Grinding wheel slide 31 may also be hydraulically actuated for rapid movement into grinding position. Such a mechanism may comprise a piston rod 324 (Figure 12) carrying a piston 325 at one end, slideable in a cylinder 326, and having its other end pass through cylinder head 327 where it can abut against a sleeve-like unit 328 in which the feed screw bearing 38 is carried and which is slideable in a cylinder-like guideway 329 formed in the machine frame. When fluid under pressure is admitted to the cylinder 326 to the right of piston 325, piston rod 324 is rapidly moved to the left and pushes the bearing-carrying sleeve 328 to the left along its guideway 329, thus moving feed screw 36 bodily, and hence also the wheel slide 31, to the left, forward shaft extension 315 of feed screw 36 sliding inwardly of the splined sleeve 314 until it engages an adjustably positioned stop element 330 on the end of a rod 331 that extends through the hollow shaft 312 to the front of the machine where suitable means are provided for controlling its setting. After such rapid forward movement of the grinding wheel to a practical grinding position, a slow precise feeding movement may be given the grinding wheel to determine its depth of cut and its final position, thus determining the final position of the grinding line GL (see Figures 16 and 17) relative to which the work-holder is rotated and bodily displaced as above described to grind the above-described blade surfaces. For further details of operation and control of the hydraulic mechanism for rapidly moving the grinding wheel forwardly to operative position, reference may be made to the above Silven Patent No. 2,522,485.

It will be understood that the number of revolutions given the work-holder W to complete the shaping of the faces F, F of the juxtaposed blades B, B carried thereby (see Figures 16 and 17) may vary according to the amount of material that has to be removed. With the work-holder W set into rotation, the grinding wheel 22 may be rapidly traversed forwardly to grinding position, as by the hydraulic mechanism 325-326 above described, whereupon during the ensuing grinding operation and continued rotation of the work-holder W the grinding wheel and its slide may be slowly fed forward at the desired grinding rate by the mechanism that controls the slow rotation of the feed screw 36 (Figure 12), thus taking successive cuts in the surface of the blades B, B, one after the other, for as many revolutions of the work-holder W as are necessary not only to shape the face F of each but also dimension or to size it in relation to the axis O-X (Figures 3, 4, and 5), the in-feed of the grinding wheel being halted at an appropriate point for the above-mentioned sizing purpose; with the grinding wheel in halted position, drive of the work-holder W may continue for one or more revolutions whereupon the wheel slide is rearwardly retracted, the drive of the head stock control unit and tail unit halted, and the work-holder W removed, whence the apparatus is ready to recommence a new grinding cycle.

Referring to Figure 1, stoppage of the drive of the head stock and tail stock control units is preferably effected by control of the circuit of driving motor 136 of the power drive unit 51;

this may be effected by hand lever 333 (Figure 1) in coaction with a snap switch 334 on a switch panel at the front of the machine base 23, and as described in the above-mentioned Silven patent; snap switch 334 (being switch 406 in the Silven patent) may be given either of two positions, in one of which the circuit of motor 136 is controlled by hand lever 333 (lever 401 in the Silven patent), movable into either start or stop position, but when the switch 334 is snapped into another position, the control of the circuit of motor 136 is removed from hand lever 333 and may be effected in timed relation with the operation of other mechanisms of the machine, for example, in timed relation with the movement of grinding wheel slide 31 into and out of operative relation to the work. Starting and stopping of such transverse movement of the grinding wheel slide 31 may be under the manual control of a hand lever 335 (being lever 391 in the Silven patent) at the front of the machine (Figure 1) and by means and mechanisms as above described in the Silven patent.

As earlier described, the block-like end elements A and C of the blade member T are utilized, in coaction with suitable engaging or securing devices on the work-holder W, to secure and position the blade member T on the work-holder W so that the above-described axis O—X (Figures 3, 4, and 5), to which the faces, surfaces, or other configurations of the end elements A and C are related by appropriate shaping, machining, grinding, or the like, is coincident with the axis of the work-holder W itself as determined by the journal boxes JL and JR (Figure 13) as above described. These end elements A and C may have any desired or needed shape or conformation, and the shape thereof as shown in Figures 13 and 14 is therefore to be understood as simply illustrative. Since the work-holder W is constructed to support two blade members T in exact juxtaposition to each other, the work-holder W, so far as concerns the clamping or securing devices for positioning the blade members T thereon, is constructed identically the same to either side of the horizontal plane through the axis O—X in Figures 14 and 15, symmetrically with respect thereto; accordingly it will suffice to describe the illustrative construction with respect to the structure on one side of that horizontal plane, the same reference characters being applicable to the parts on the other side thereof.

The work-holder W has a central shank 340 (Figures 13 and 14) which may be square or rectangular in cross-section and lengthwise of a face 341 of which, but structurally spaced therefrom, the blade B of the blade member T is to overlie. At its right-hand end shank 340 widens out (see also Figure 6) both horizontally and vertically, being milled out to provide a recess 342 formed by opposed walls 343, 344 (Figure 14), and a relatively thick end wall 345, the block-like end element C of blade member T being receivable in recess 342. One face of element C engages wall 343 and the opposite face engages a locating screw 354 that extends through wall 344 and is provided with a lock nut. In this illustrative embodiment end element C has a transverse hole of peculiar angularity, indicated in Figure 14, and accordingly opposed side walls 343 and 344 are provided with correspondingly angled but aligned holes through which a dowel or pin 346 is thrust provided with a knurled head 347 for ease of handling and releasably held against re-

moval by any suitable means. For example, the dowel pin 346 may have a peripheral groove 346a cut therein (Figure 14) into which the pin-like end of a plunger 347 is entered, slidably carried in a hole 348 in the work-holder part and yieldably pressed toward the pin by a spring 350 in the hole 348 which is closed at its outer end by a screw-threaded plug 351. Pin 346 is thus readily removable. It aids in fixing the position of the right end of blade member T relative to the work-holder axis O—X as seen in Figure 13. As is better shown in Figure 13, the right end of the work-holder W carries a clamping block 355 that overlies the recess 342 in which element C is received; its clamping end has an adjustable screw 356 engageable with another face end element C, clamping block 355 being manually controllable by a wing nut 357 threaded onto a stud screw 358 that extends from the work-holder and through a suitable hole or slot in the clamping block.

The left end of work-holder shank 340 also widens out and is milled out to provide a recess 360, in general like recess 342 at the other end, recess 360 having opposed walls 361 and 362 (Figure 14) and an end wall 363. Block-like end element A is received in recess 360 between opposed side walls 361, 362 and has a part or face that rests against the bottom of recess 360 as viewed in Figure 13, thus fixing the left end of blade member T in a direction toward or away from the work-holder axis O—X and being held in that position by a clamping block 364 provided at one end with an adjustable and lockable clamping screw 365 and held in clamping relation by a wing nut 366 on a stud screw 367 that extends from the end wall part 363 and through a suitable hole in the clamping block itself. Side wall part 362 (Figure 14) is provided with an adjustable screw 368 between which and side wall part 361 opposite side parts or faces of the end block element A are received, thus positioning the left end of blade member T transversely of the work-holder axis O—X as viewed in Figure 14.

It is in such manner that the blade members T, with block-like end elements A and C provided with appropriately machined or finished faces, parts, or the like, are quickly and detachably related and secured to the work-holder and the axes of the parts thus also quickly brought into coincidence, as above described. For example, to replace a blade member T, only clamping blocks 364 and 355 need be manipulated and, of course, also dowel pin 346 where a blade end element has a hole therethrough in relation to which the work blade curvature must also be determined.

Because of the relatively small angle subtended by the face F of the blade B, as viewed in Figures 16 and 17 or in Figures 3, 4, and 5, it is possible, as will now be clear in view of the foregoing, to assemble more than one blade member T to the universally shiftable centers CL and CR (Figure 6) for controlled cutting action on their respective faces, and in the illustration given and described above, two blade members T are so assembled to these centers with the aid of the above-described work-holder W and in the latter case the cam units of the head-stock control unit and tail-stock control unit make two revolutions for each revolution of the work-supporting centers and work-holder; as above described, this ratio of drive is achieved by making the gear 145 (Figures 7 and 8) of twice the pitch diameter of the gear 146. It will now be apparent that

this ratio of drive is changeable or variable according to the number of work-pieces which it is possible to assemble about the axis O—X and to the supporting centers. For example, were the surface to be shaped to subtend an angle on the order of greater than 180 degrees so that only one work-piece or blade element T can be accommodated and rotatably supported by the two centers, the ratio of drive would be made 1:1.

Also it will be understood that the specific forms of cams to control the respective positions of the centers horizontally and vertically are illustrative and may be varied according to requirements to determine the extent and direction of displacement of either or both of the supporting centers; for example, as will now be clear, the surface to be formed may require universal shift of one center and no shift of the other supporting center, and in such case the two cams controlling the former are shaped to give the desired horizontal and vertical components of shift while the cams controlling the latter are shaped, as by making them circular, to convey neither horizontal nor vertical components of shift thereto. The four cams LH, RH, RV, and LV, by appropriate relative shaping, provide a wide range of control of supporting centers in relation to each other and to the grinding line, and thus the apparatus is well adapted to meet a wide variety of practical requirements.

By so shaping the cams in relation to each other and to the grinding line, the work-piece, whose axis of rotation is determined by the centers CL and CR whether it is directly supported thereon or indirectly supported thereon as through a work-holder, may be faired according to the shape of that grinding line which, in the specific illustration described above, is a straight line but which, as also earlier set forth above, can be suitably curved by appropriately shaping the peripheral face of the grinding wheel. In either case I am enabled to achieve still further variety of surface shaping in that, again by appropriate relative shaping of the cams, I am enabled also to so shift or angularly tilt the work axis as to bring into action on any desired part or even the whole of the surface to be shaped a different grinding line than the one illustratively set forth as lying in the horizontal plane through the grinding wheel axis.

For example, let it be assumed that the grinding wheel is trued to provide a straight grinding line in that horizontal plane, as in the specific illustration fully described above; so long as the control cams prevent the work surface from engaging the grinding wheel face in other than that straight grinding line of contact, the surface is straight line faired throughout whatever controlled wobble is transmitted to the work axis, as is fully described above, but by appropriately shaping the cams I can cause the entire work surface or any arcuate portion thereof to be concaved without changing the shape of the grinding wheel face by causing the cams to effect such tilt of the work axis and the selected portion or portions of the work surface as is presented to the grinding wheel to cause the latter to engage the work surface not in the straight grinding line GL but in a line that is angled or skewed relative to that straight grinding line GL; as a result of such tilt or skewing the grinding line of contact with the work surface is slightly concaved and the fairing corresponds thereto and to such variations thereof as the shaping of the cams determines as, for example,

when a straight line fairing is to merge into a concavely faired portion, or vice versa. In broadly similar manner, where the grinding wheel face is shaped as by giving it a desired curvature at the grinding line GL, departures from that shaping can be controllably effected when and where desired by controlling what might be called the angle of skew. For example, the grinding wheel face might be shaped slightly concave so that at the grinding line in the horizontal plane through the grinding wheel axis the surface of the work-piece is ground to complementary convex shape or curvature from which departures may be effected, by the control cams, to the desired extent and even to straight line fairing when the just-mentioned angle of skew relative to the slightly concave grinding wheel face is such that the line of contact with the work surface is a straight line.

It will thus be seen that there has been provided in this invention an apparatus for shaping surfaces of peculiar or unusual geometrical configurations and in which the several objects above noted, together with many thoroughly practical advantages, are successfully achieved. It will be seen that the apparatus is of a thoroughly practical nature and that it is of a construction and arrangement that lends itself to wide flexibility and adaptation to meet a wide range of conditions or requirements according to the particular shape to be given the surface of the blade or like part.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

What is claimed is:

1. In a machine for shaping surfaces, in combination, a base having a longitudinally extending table with guideways extending lengthwise thereof and having ways extending transversely of said table, a wheel slide movably supported by said last-mentioned ways and rotatably supporting a peripherally operative grinding wheel with its axis substantially parallel to said first-mentioned ways, a power drive head and a head stock control unit and a tail stock control unit arranged in that order along said table guideways, said two units having at their adjacent ends supporting centers whereby a work-piece may be supported for action thereon by said grinding wheel, each of said supporting centers being carried at the lower end of a substantially vertical pendent arm which is pivotally suspended from one end of a substantially horizontal arm of which the other end is pivotally supported by the unit of which the supporting center is a part, each of said units having two cams co-acting respectively with the horizontal arm and the vertical arm of the unit whereby each of said centers is universally displaceable and independently of the other in accordance with the amount of vertical components and horizontal components of movement transmitted to the horizontal arms and the vertical arms respectively by their respective cams, a work driving dog associated with the center of said head stock control unit and partaking of movement of displacement communicated to said center, driving connections between said power drive head and

33

said driving dog, drive shaft means extending between said two units and having, in each unit, driving connections with the two cams thereon, a driving connection between said power drive head and said drive shaft means, and means operating upon at least one of said supporting centers to yieldingly urge it toward the other supporting center to compensate for lessening of the effective axial length of the work as the axis of the latter is shifted out of parallelism with the axis of the grinding wheel.

2. A machine as claimed in claim 1 in which said drive shaft means comprises a jack shaft in each of said units with coupling means between said two jack shafts provided with means for rotatively shifting one of said jack shafts relative to the other to facilitate timing of the cams in one unit relative to the cams of the other unit.

3. An apparatus as claimed in claim 2 in which the two cams of one of said units are individual of each other and are provided with means for rotatively shifting one of them relative to the other to co-relate their effects upon the arms with which they respectively coat.

4. An apparatus as claimed in claim 2 in which the two cams of each of said units are individual of each other and are provided with means for rotatively shifting each of them relative to the other to co-relate their effects upon the arms with which they respectively coat.

5. An apparatus as claimed in claim 1 in which the driving connections between said drive shaft means and the cams of said units comprise gears and friction-brake means exerting a drag on the rotation of the cams.

6. An apparatus as claimed in claim 1 in which said last-mentioned means comprises an axially movable slide member slidably guided in the pendent arm and having the supporting center at one end thereof with spring means operative at the other end thereof to yieldingly stress said slide member and its supporting center toward the other supporting center.

7. An apparatus as claimed in claim 6 provided with manually controllable means accessible from the exterior of the control unit for retracting said slide member and its supporting center against the action of said spring.

8. An apparatus as claimed in claim 1 in which said last-mentioned means comprises a sleeve internally tapered at one end to form a tapered seat for said supporting center, the pendent arm having a bore for slidably supporting said sleeve, with a helical spring coacting at the other end of said sleeve to urge the latter and its supporting center toward the other supporting center, and a hydraulic motor for withdrawing the sleeve against the action of said spring and valve means for controlling the motor.

9. An apparatus as claimed in claim 8 in which said hydraulic motor comprises a piston and cylinder carried by the pendent arm and coaxially aligned with said sleeve, the motor having a tubular piston rod connected at one end to the piston and connected at the other end to said sleeve whereby a rod may be inserted through the hollow piston rod and sleeve to knock out the supporting center.

10. An apparatus as claimed in claim 1 in which each of said units has a cam shaft with the two cams thereof coaxially supported on the cam shaft, said driving connections between said drive shaft means and the cams of each unit comprising the respective cam shafts of the units and

34

gears connecting each cam shaft to said drive shaft means.

11. An apparatus as claimed in claim 10 in which the two cams coaxially mounted on the cam shaft of one of said units comprise coaxial hubs of which one is keyed to the cam shaft to fix the relation of its cam thereto, and means coacting between the latter cam and the other hub for securing them together in selected rotative position of one relative to the other.

12. An apparatus as claimed in claim 10 in which the two cams coaxially mounted on the cam shaft of one of said units comprise concentric sleeve-like hubs with one received within the other, with key means coacting between the cam shaft and the inner hub to non-rotatively lock one cam relative to the cam shaft, and means coacting between the latter cam and the outer hub for securing the two cams together in selected rotative position of the one relative to the other.

13. In an apparatus for shaping surfaces, in combination, a peripherally operative grinding wheel having a shaped grinding face to provide, in the horizontal plane through its axis, a correspondingly defined horizontal grinding line of contact across its face for action on a work-piece, work-piece supporting and rotating means comprising a work-holder having end bearing

means determining an axis therefor and having means for mounting a work-piece thereon in relation to said axis, two axially spaced supporting centers at substantially the height of said horizontal plane and with a line joining them spaced from said grinding line of contact, for respective interengagement with said end bearing means for thereby fixing said axis as an axis of rotation for said work-holder and the work-piece supported thereby whereby said axis of rotation is displaced from said grinding line to extend in the general direction thereof, each of said supporting centers having means mounting it for bodily movement in any direction substantially parallel to itself whereby each supporting center may be displaced

in any direction independently of the other and thereby effect universal shift of said axis of rotation relative to said defined grinding line, drive means for rotating said work-holder and its supported work-piece thereby to traverse successive longitudinal peripheral portions of the work-piece relative to said grinding wheel, and two control means operating respectively upon the mounting means for said two supporting centers to determine the respective amounts and directions of displacement of the two supporting centers relative to each other and relative to said defined grinding line to present said successive peripheral portions of the work-piece for cutting engagement with the grinding wheel only at said defined grinding line of the latter.

14. An apparatus according to claim 13 in which each of said center-mounting means comprises a center support having means movably supporting it for movement horizontally toward or away from said grinding line and for movement vertically whereby direction and amount of center displacement are the resultant of the respective horizontal and vertical components of movement given the center support, said two control means each comprising correlated elements which respectively determine the amounts of horizontal and vertical displacements of the center support.

15. An apparatus according to claim 13 in which each of said center-mounting means com-

prises two pivotally connected arms making an angle with each other on the order of 90 degrees, the free end of one of said arms having means pivotally supporting it to move about an axis substantially parallel to said grinding line and the free end of the other arm having means for supporting the supporting center, and each of said two control means comprises two control elements one of which operates upon one of said arms and the other of which operates upon the other of said arms to control the respective amounts and directions of displacement of the two arms and thereby correspondingly control the direction and amount of displacement of the supporting center.

16. In an apparatus for shaping surfaces, in combination, a peripherally operative grinding wheel having a shaped grinding face to provide in the horizontal plane through its axis a correspondingly defined horizontal grinding line of contact across its face for action on a work-piece, work-holding and supporting means comprising two axially spaced supporting centers at substantially the height of said horizontal plane and with a line joining them spaced from said grinding line of contact, for fixing the axis of rotation of a work-piece, means movably supporting said centers for tilting, throughout a substantial range, of the axis fixed by them in any direction relative to said grinding line, means for rotating a work-piece whose axis is fixed by said supporting centers to traverse successive longitudinal peripheral portions of the work-piece relative to the grinding wheel, and means operating in timed relation to the rotary traversing movement of the work-piece relative to the grinding wheel and operating upon said center-supporting means to select and determine, increment by increment of rotary traversing movement and respectively within the aforesaid range of directions and range of tilting, the direction and amount of tilt of said axis relative to said grinding line to give the work-piece a surface successive longitudinal increments of which are conformed to said grinding line even though their angularity to said axis varies.

17. In an apparatus for shaping surfaces, in combination, a peripherally operative grinding wheel having a shaped grinding face to provide in the horizontal plane through its axis a correspondingly defined horizontal grinding line of contact across its face for action on a work-piece, two axially spaced supporting centers at substantially the height of said horizontal plane and with a line joining them spaced from said grinding line of contact, for fixing the axis of rotation of a work-piece, means movably supporting at least one of said centers for bodily movement of substantial range in any direction taken in a plane substantially transverse to said axis of rotation whereby to tilt said axis in any direction relative to said horizontal grinding line, means for driving a work-piece about said axis to traverse successive longitudinal peripheral portions thereof relative to the grinding wheel, and means operating upon said movable supporting means and during the rotary traversing movement of the work-piece relative to the grinding wheel to determine the direction and to select the amount, from zero upwardly, of said range of bodily movement of said movably supported center relative to the other.

18. In an apparatus for shaping surfaces, in combination, a peripherally operative grinding wheel having a shaped grinding face to provide,

in a plane through its axis, a correspondingly defined grinding line of contact across its face for action on a work-piece, two axially spaced supporting centers positioned so that a line joining them falls substantially in said plane and is spaced from said grinding line of contact, for fixing the axis of rotation of a work-piece, each of said supporting centers having means mounting it for bodily movement in any direction substantially parallel to itself whereby each supporting center may be displaced in any direction independently of the other and thereby effect universal bodily and angularly shift of said axis of rotation relative to said defined grinding line, at least one of said mounting means having means for yieldingly shifting it axially toward or away from the other of said centers, means for driving a work-piece about said axis to traverse successive longitudinal peripheral portions thereof relative to the grinding wheel, and means operating during rotary traversing movement of the work-piece relative to the grinding wheel and operating upon each of said center-supporting means to determine the direction and amount of bodily displacement of the supporting center.

19. In an apparatus for shaping surfaces, in combination, a peripherally operative grinding wheel having a shaped grinding face to provide in the horizontal plane through its axis a correspondingly defined horizontal grinding line of contact across its face for action on a work-piece, means for supporting and rotating a work-piece and providing an axis of rotation for the work-piece with said axis at substantially the height of said horizontal plane and extending in a direction generally parallel to said defined grinding line whereby to traverse successive longitudinal peripheral portions of the work-piece relative to the grinding wheel, said work-supporting and rotating means being movable for universally tilting the axis of rotation of the work-piece relative to said grinding wheel in that the said means has two axially spaced universally movable supports therefor each of which has means movably supporting it for movement in all directions in a plane transverse to said grinding line, and two control means operating respectively upon said axially spaced universally movable supports for determining the directions and amounts of movement of each relative to the other and each in substantially a plane transverse to said grinding line and thereby determining tilt of the axis of rotation of the work-piece relative to both the horizontal and the vertical.

20. In an apparatus for shaping surfaces, in combination, a peripherally operative grinding wheel having a shaped grinding face to provide in the horizontal plane through its axis a correspondingly defined horizontal grinding line of contact across its face for action on a work-piece, shiftable means for supporting and rotating a work-piece and providing an axis of rotation for the work-piece with said axis at substantially the height of said horizontal plane and extending in a direction generally parallel to said defined grinding line whereby to traverse successive longitudinal peripheral portions of the work-piece relative to the grinding wheel, said shiftable work-supporting and rotating means having axially spaced supports therefor which are movable throughout a substantial range in all directions taken in a plane transverse to said axis, and means operating upon said spaced supports during rotary traversing movement of the work-piece for determining the respective directions

and amounts of movement thereof to present said successive peripheral portions of the work-piece for cutting engagement with the grinding wheel only at said defined grinding line.

21. In an apparatus for shaping surfaces, in combination, a peripherally operative grinding wheel having a shaped grinding face to provide in the horizontal plane through its axis a correspondingly defined horizontal grinding line of contact across its face for action on a work-piece, two axially spaced supporting centers at substantially the height of said horizontal plane and with a line joining them spaced from said grinding line of contact, for fixing the axis of rotation of a work-piece, means, one for each of said centers, movably supporting the center for substantial ranges of bodily movement in horizontal direction and in vertical direction whereby each of said centers may be bodily moved in said directions independently of the other to tilt said work-piece axis in any direction relative to said horizontal grinding line, means for driving a work-piece about said axis to traverse successive longitudinal peripheral portions thereof relative to the grinding wheel face, and means operating upon said movable center supporting means and in timed relation to the rotary traversing movement of the work-piece about its axis to determine the respective amounts of horizontal movement and vertical movement transmitted to each center.

22. In a machine for shaping surfaces, in combination, a base having longitudinally extending guideways, a grinding wheel rotatably supported adjacent thereto, a head-stock unit and a tail-stock unit spaced along said guideways, said two units having at their adjacent ends supporting centers whereby a work-piece may be supported for action thereon by said grinding wheel with a work driving dog associated with at least one of said supporting centers, each of said units having means movably supporting its supporting center for substantial range of bodily movement in any direction while maintaining it substantially parallel to itself whereby each center is movable in said directions independently of the other, and power-driven means operating upon each of said movable center-supporting means and during grinding action of said grinding wheel upon a work-piece rotated by said driving dog, for controlling the direction and determining the extent of movement, each relative to the other, of said center-supporting means within said range of bodily movement.

23. In a machine for shaping surfaces, in combination, a base having longitudinally extending guideways, a grinding wheel rotatably supported adjacent thereto, a head-stock unit and a tail-stock unit spaced along said guideways, said two units having at their adjacent ends supporting centers whereby a work-piece may be supported for action thereon by said grinding wheel and at least one of said units having means for rotating the work-piece during grinding action, each of said units having means movably supporting its center for substantial ranges of displacement both vertically and horizontally whereby each center is movable both vertically and horizontally independently of the other, and two means operating in timed relation to each other and to said work-rotating means for controlling the direction and respective amounts of horizontal movement and of vertical movement, each relative to the other, of each of said movable center-supporting means within the aforesaid respective

substantial ranges of vertical and horizontal displacement.

24. In a machine for shaping surfaces, in combination, a base having longitudinally extending guideways, a grinding wheel rotatably supported adjacent thereto, a head-stock unit and a tail-stock unit spaced along said guideways, said two units having at their adjacent ends supporting centers whereby a work-piece may be supported for action thereon by said grinding wheel and at least one of said units having means for rotating the work-piece during grinding action, at least one of said units having means movably supporting its center for displacement both vertically and horizontally, and means operating in timed relation to said work-rotating means for controlling the direction and amount of horizontal movement and of vertical movement of said movable center-supporting means, said last-mentioned means that operates in timed relation to said work-rotating means comprising two cams coacting with said movable center-supporting means, one of said cams coacting to control the extent and direction of movement horizontally and the other controlling the direction and extent of movement vertically, with driving connections between said work-rotating means and said two cams to time the drive of said cams with the drive of said work-rotating means.

25. In a machine for shaping surfaces, in combination, a base having longitudinally extending guideways, a grinding wheel rotatably supported adjacent thereto, a head-stock unit and a tail-stock unit spaced along said guideways, said two units having at their adjacent ends supporting centers whereby a work-piece may be supported for action thereon by said grinding wheel and at least one of said units having means for rotating the work-piece during grinding action, at least one of said units having its center supported in the free end of one of two pivotally connected arms of which the free end of the other arm is pivotally supported in the unit and of which one arm extends horizontally and the other extends vertically, and power-driven means synchronized with said work-rotating means and coacting with said vertical arm and said horizontal arm to control swinging movement of the former and swinging movement of the latter whereby the direction and magnitude of shift of the supporting center is the resultant of the horizontal component of movement transmitted by said vertical arm and the vertical component of movement transmitted by said horizontal arm.

26. A grinding machine as claimed in claim 25 in which said synchronized power-driven means comprises two rotating cams coacting respectively with said vertical arm and said horizontal arm and having contours corresponding respectively to the magnitudes and directions of said horizontal components and vertical components of movement.

27. In a machine for shaping surfaces, in combination, a base having longitudinally extending guideways, a grinding wheel rotatably supported adjacent thereto, a head-stock unit and a tail-stock unit spaced along said guideways, said two units having at their adjacent ends supporting centers whereby a work-piece may be supported for action thereon by said grinding wheel and at least one of said units having means for rotating the work-piece during grinding action, at least one of said units having its center supported in the lower end of a substantially vertical pendent arm which is pivotally suspended from one end

of a substantially horizontal arm of which the other end is pivotally supported by the unit, a rotatable cam underneath said vertical arm, a rotatable cam coacting with said horizontal arm, and means for driving said two cams in timed relation with said work-rotating means.

28. A grinding machine as claimed in claim 27 in which the unit that has said horizontal arm and said vertical arm is provided with means for disengaging said horizontal arm from the cam underneath it, said means comprising two parts carried respectively by said unit and by said horizontal arm and provided with means for interengaging them and holding said horizontal arm in position raised upon its cam.

29. A machine as claimed in claim 28 in which one of said two parts is threaded and the said interengaging means comprises a threaded part whereby upon relative rotary movement therebetween the one part is threaded into the other and said horizontal arm is raised and held above its cam.

30. A machine as claimed in claim 28 in which one of said two parts is in the form of a threaded nut and said interengaging means comprises a 25 threaded shank whereby upon relative rotary movement therebetween said horizontal arm is raised and held above its cam.

31. A machine as claimed in claim 27 in which said vertical arm is provided with a cam follower coacting with its cam and is provided with means exerting a yieldable force on the arm to hold its cam follower always in coacting contact with its cam.

32. A machine as claimed in claim 31 in which said force-exerting means comprises a spring anchored at one end to said vertical arm and having at its other end a readily releasable anchorage to a stationary part of said unit.

33. A machine as claimed in claim 32 in which said readily releasable anchorage comprises two pivotally connected links, said part of said unit having a guideway for slidably receiving said links to an extent determined by whether or not the more remote of the two pivotally connected links is aligned with the other or is swung transversely thereto.

34. In a machine for shaping surfaces, in combination, a base supporting a grinding wheel and having means for supporting and rotating a work-piece for action thereon by said grinding wheel and for universally tilting the axis of the work-piece relative to said grinding wheel, said means comprising two spaced ball-ended supporting centers for fixing the axis of rotation of the work-piece, means movably supporting at least one of said centers for movement in any direction taken in a plane substantially transverse to said axis, means synchronized with the rotation of the work-piece and operating upon said movable center-supporting means for controlling the direction and extent of movement thereof, and means mounting at least one of said supporting centers to yieldingly urge it toward the other supporting center to compensate for change in the projected spacing between said two ball-ended centers as said movably supported center is moved to tilt the axis of rotation of the work-piece.

35. A machine as claimed in claim 34 in which said means yieldingly urging one center toward the other comprises an axially movable slide member supporting the center with spring means acting upon said slide member to urge it and the center toward the other supporting center.

36. A machine as claimed in claim 35 provided with manually controllable means for retracting said slide member and its center against action of said spring means.

37. A machine as claimed in claim 35 in which said slide member is provided with means for controlling its position against the action of said spring means in the form of a hydraulic motor which comprises a piston member and a cylinder member one of which is connected to said slide member.

38. In a machine for shaping surfaces, in combination, a base supporting a grinding wheel and having means for supporting and rotating a work-piece for action thereon by said grinding wheel and for universally tilting the axis of the work-piece relative to said grinding wheel, said means comprising two spaced ball-ended supporting centers for fixing the axis of rotation of the work-piece and a work driving dog associated with one of said centers with a carrier for each of said centers having means movably supporting it for movement in any direction taken in a plane substantially transverse to said axis, each of said carriers having associated therewith driven control means for determining the direction and extent of movement of the carrier, the mounting means for at least one of said carriers including guiding means permitting movement thereof in a direction toward and away from the other carrier with means operating thereon to yieldingly urge it and its center toward the other carrier and its center to compensate for change in the projected spacing between said two ball-ended centers as relative movement therebetween takes place to tilt the axis of rotation of the work-piece, drive means for said driving dog, and means for coordinating said driven control means with said dog drive means.

39. A machine as claimed in claim 38 in which said coordinating means comprises disconnectible driving connections between said dog driving means and said driven control means and means for dogging one of them upon disconnection with said driving connection to permit rotative adjustment of the other relative thereto.

40. A machine as claimed in claim 38 in which said coordinating means comprises disconnectible driving connections between said dog driving means and said driven control means and means for dogging one of them upon disconnection with said driving connection to permit rotative adjustment of the other relative thereto, together with adjustable and releasable dogging means for said other and adapted to be adjusted for releasable dogging upon conclusion of said rotative adjustment.

41. A machine as claimed in claim 38 in which said coordinating means comprises driving connections between said two driven control means having manually controllable means for rotatively shifting one relative to the other.

42. A machine as claimed in claim 38 in which the means for movably supporting each carrier comprises two supporting elements of which one supports the carrier and is mechanically connected to the other for reversible movement in one direction taken in said transverse plane and the other has means guiding it for reversible movement in a direction substantially 90 degrees to said last-mentioned direction whereby the movement of the carrier is in direction and extent the resultant of components of movement respectively transmitted thereto by said supporting elements, each of said driven control means

comprising two cam elements operating respectively upon said two supporting elements to determine the respective directions and extents of said components of movement.

43. In a machine for shaping surfaces, in combination, a base supporting a grinding wheel and having means for supporting and rotating a work-piece for action thereon by said grinding wheel and for universally tilting the axis of the work-piece relative to said grinding wheel, said means comprising two axially spaced supporting centers for fixing the axis of rotation of the work-piece and means supporting at least one of said centers for movement in any direction taken in a plane substantially transverse to said axis and comprising two supporting elements of which one supports the center and is mechanically connected to the other for reversible movement in one direction taken in said transverse plane and the other has means guiding it for reversible movement in a direction substantially 90 degrees to said last-mentioned direction whereby the movement of the center is in direction and extent the resultant of components of movement respectively transmitted thereto by said supporting elements, and power-driven means synchro-

nized with the rotation of the work-piece and comprising two control means operating respectively upon said two supporting elements for determining the directions and magnitudes of their respective movements.

CLARENCE J. GREEN.
